poration of Delaware

Application May 18, 1934, Serial No. 726,346

55 Claims.

(Cl. 93—2)

This invention relates to wrapping machines and more particularly to wrapping machines suitable for wrapping sliced and unsliced bread and other rectangular shaped articles.

5 One of the objects of the present invention is to provide a wrapping machine in which the wrapping material is fed substantially continuously except during a momentary period when a sheet of predetermined length is severed therefrom, and also in which the rate of feeding movement accelerates and decelerates respectively just after and just before the severing operation.

Another object is to provide a wrapping machine in which the location of the overlapping ends of the sheet of wrapping material with respect to a surface of the article being wrapped can be predetermined.

Another object is to provide a wrapping machine with means for feeding wrapping material in which the means is bodily movable for predetermining the discharge position of the wrapping material, and in which such means will not cause feeding of the wrapping material during such movement.

Another object is to provide a wrapping machine having a means for feeding wrapping material and supporting means for moving an article to a wrapping position with additional means which functions to cause operation of the feeding means and supporting means only when an article is being moved onto the supporting means.

Another object is to provide means in a wrapping machine for starting a wrapping material feeding means in operation only upon the feeding of an unwrapped article into the wrapping machine.

Another object is to provide a cooling device for wrapping machines of new and improved construction by means of which the sealing material of overlapped portions of the wrapper can be very rapidly congealed to form an efficient seal.

Another object is to provide a wrapping machine with a new and improved means for heating the overlapped surfaces of the wrapper.

Another object is to provide a wrapping machine with a reciprocable member for folding an end portion of wrapping material against a surface of the article being wrapped and which member is provided with a means which operates independently of and during the folding movement to smooth out the end portion being folded.

Another object is to provide a wrapping machine with new and improved mechanism for

forming end folds having creased edges so as to provide substantially square corners in the wrapper.

A further object is to provide a wrapping machine with mechanism for carrying wrapping material being advanced by a feeding means to a wrapping position, and in which the paper is held under a slight tension during such carrying movement.

Other objects will be apparent from the following detailed description which is made with reference to the accompanying drawings which illustrate a suitable embodiment of the invention.

In the drawings:

Figure 1 is a side elevation of the wrapping machine of the present invention;

Fig. 2 is a view similar to Fig. 1 with one of the side frames removed to clearly show the operating parts of the wrapping machine shown in Fig. 1;

Fig. 24 is a plan view of the cutter employed for severing the wrapping material;

Fig. 25 is a front elevation of the cutter illustrated in Fig. 24;

Fig. 26 is an enlarged section through the cutter taken approximately on the line 26—26 of Fig. 24;

Fig. 27 is a sectional view showing the feed rolls and elevating means for the wrapping material, and also showing the knife or cutter which severs the wrapping material;

Fig. 28 is a fragmentary view similar to Fig. 27, but showing the feed rolls and elevating mechanism in adjusted position;

Fig. 29 is a view similar to Fig. 28, but showing the elevating mechanism in another operative position;

Fig. 30 is a section taken approximately on the line 30—30 of Fig. 27;

Fig. 31 is an enlarged section taken approximately on the line 31—31 of Fig. 3, showing the Geneva gear which operates the carrier for the wrapping material;

Fig. 32 is a section taken approximately on the line 32—32 of Fig. 31;

Fig. 33 is a section taken approximately on the line 33—33 of Fig. 2, showing the adjustable drive mechanism in elevation;

Fig. 34 is an enlarged section taken approximately on the line 34—34 of Fig. 33, showing the adjustable drive pulley carried by the drive motor;

Fig. 35 is a side elevation partially in section of the wiping mechanism for the wrapping material;

Fig. 36 is a view similar to Fig. 35, showing another position of the wiping mechanism;

Fig. 37 is a view similar to Figs. 35 and 36, showing a further position of the wiping mechanism;

Fig. 38 is a vertical section taken approximately on the line 38—38 of Fig. 35;

Fig. 39 is an enlarged elevation of the end grippers illustrated in Fig. 3, which grip the ends of the article being wrapped, and form the top fold at the end of the article;

Fig. 39a is a section taken approximately on the line 39a—39a of Fig. 39;

Fig. 40 is an enlarged side elevation of the movable bread carriers and the mechanism for operating the same;

Fig. 41 is a horizontal section taken approximately on the line 41—41 of Fig. 40;

Fig. 42 is a vertical section taken approximately on the line 42—42 of Fig. 40;

Fig. 43 is a view of the bread carrier taken looking in the direction of the arrows 43—43 of Fig. 40;

Fig. 44 is a side elevation of the mechanism for forming the bottom fold in the wrapping material, and also forming the rear end folds in the wrapping material;

Fig. 45 is a section taken approximately on the line 45—45 of Fig. 44;

Fig. 46 is a horizontal section taken approximately on the line 46—46 of Fig. 44;

Fig. 47 is a view similar to Fig. 44 showing the end tuckers in a forward position;

Fig. 48 is a view of the mechanism illustrated in Fig. 44, taken as looking in the direction of the arrows 48—48 in Fig. 44;

Fig. 49 is a side elevation of one of the end tuckers showing the same in the operation of forming the rear end fold;

Fig. 50 is a front elevation of the end tucker and article illustrated in Fig. 49;

Fig. 51 is a plan view of the tucker and article illustrated in Figs. 49 and 50;

Fig. 52 is a side elevation of the mechanism for limiting the stroke of the spring pressed arm shown in Fig. 44;

Fig. 53 is a view similar to Fig. 44 but showing the bottom folder in a forward position;

Fig. 54 is a section taken approximately on the line 54—54 of Fig. 53, showing one of the rolls employed for ironing out the wrapping material comprising the bottom fold;

Fig. 55 is an elevation of the adjusting mechanism shown in Fig. 52;

Figs. 56, 56a, 57, and 58, are four diagrammatic views showing different positions of the wrapping material in its progress through the wrapping machine;

Fig. 59 is a fragmentary end view showing the position of the article and the wrapping material just subsequent to the formation of the upper end fold;

Fig. 60 is a diagrammatic view showing the formation of the rear end fold and the bottom lap of the wrapping material;

Fig. 61 is a diagrammatic view showing the article being wrapped and the wrapping material during the formation of the forward bottom lap and prior to the formation of the forward end fold;

Fig. 62 is a diagrammatic view showing the article being wrapped and the wrapping material after the formation of the forward end fold and prior to the formation of the bottom end fold;

Fig. 63 is a diagrammatic view looking longitudinally of the article being wrapped and showing the bottom end fold in the process of formation;

Fig. 64 is an end view showing the completed folds at the end of the article being wrapped;

Fig. 65 is a side elevation showing the bottom end fold in the process of formation;

Fig. 66 is a section taken approximately on the line 66—66 of Fig. 65;

Fig. 67 is a transverse section through the heating plates, taken approximately on the line 67—67 of Fig. 72;

Fig. 68 is an enlarged side elevation of the heating mechanism, portions of the same being shown in section;

Figs. 69, 70, and 71 are sections taken, respectively, upon the lines 69—69, 70—70, and 71—71 of Fig. 68;

Fig. 72 is an enlarged fragmentary plan view of the wrapping machine showing the wrapper;

heating mechanism and the mechanism for cooling the sealed portions of the wrapper;

Figs. 73, 74, and 75 are transverse sections taken, respectively, on the lines 73—73, 74—74, 5 and 75—75 of Fig. 72;

Fig. 76 is a plan view of the bottom cooling chamber, the article conveying plates being removed;

Fig. 77 is an enlarged section taken approximately on the line 77—77 of Fig. 72;

Fig. 78 is a transverse section taken approximately on the line 78—78 of Fig. 77;

Fig. 79 is a section taken approximately on the line 79—79 of Fig. 77;

Fig. 80 is a diagrammatic view of the mechanism for cooling the sealed portions of the wrapper;

Fig. 81 is a fragmentary view of a modified means for assisting in the formation of a rear 20 bottom fold;

Fig. 82 is a section of the means for supporting and trimming the edges of the wrapping material;

Fig. 83 is a plan view of the means shown in Fig. 82; and

Fig. 84 is a side elevation of a device for indicating when the supply of wrapping material is about exhausted.

Referring to the accompanying drawings in which like numerals refer to like parts throughout 30 the several views, the main frame of the wrapping machine of the present invention comprises spaced side frames 1 and lower and upper connecting members 2 and 3, respectively, which carry the complete wrapping mechanism.

The paper feed mechanism infeed conveyor, article feed mechanism, and wrapping mechanism, are driven from a main drive shaft 4 which is journaled in suitable bearings 5 carried by the main frame at the lower portion thereof. 40 The main drive shaft 4 is provided at one end with a hub 6 rotatably mounted thereon, which carries a freely rotatable drive pulley 7 and a clutch device. As shown in Figs. 3, 10 and 11, the clutch device comprises an annular support 8 mounted for rotation on the hub 6 and having oppositely extending arms 9. Each arm 9 has a clutch shoe 10 pivoted thereto by means of a pivot pin 11, the opposite end of the shoe having a pivot actuator pin 12 which is slidably disposed 50 in a lug 13 formed on the opposite arm, a spring 14 being carried on the actuator pin 12 to engage the projection 13 and cause the shoe to tend to engage with a clutch drum 15 carried by the drive pulley 7. Levers 16 are pivoted on the pins 11 and receive the projecting ends of the actuator pins 12 to engage with stops 17 at the outer ends of the pins 12 so that upon movement of the arms 16 outwardly the actuator pins 12 will cause disengagement of the clutch shoes 10 from the 60 clutch drum 15. The inner ends of the lever 16 normally engage the drive shaft 4 and are provided with opposed arcuate recesses 18 which are disposed to receive a conical actuator 19 which is slidably mounted on the end of the shaft 4, that 65 projects beyond the hub 6. The conical actuator 19 is provided with a circumferential groove 20 which loosely receives suitable arms 21 provided on an actuator control lever 22 mounted on the outside of the framework. By turning the handle 70 23 of the control lever 22 (Fig. 1) the clutch shoes 10 can be actuated to provide a driving or non-driving connection between the drive pulley 7 and the annular support 8.

In order to provide a safety factor, the connection between the clutch support 8 and the drive

shaft hub 6 is preferably obtained through a spring pressed drive pin 24 having a conical end which is normally disposed to seat in a recess 24a in the hub 6 (Fig. 11), and provide driving engagement between the hub 6 and clutch support 8. 5 If the machine should fail to function when the clutch is thrown into operative position, such as from some mechanical difficulty, the drive pin 24 will automatically move from its opening in the hub and permit free rotation of the drive pulley 7 about the hub, even though the clutch is in its operative position, to thus eliminate any danger of breaking any of the operative parts of the wrapping machine. An adjusting screw 24b is provided for adjusting the tension of spring 24c 15 which is engaged with the end of drive pin 24, so that the tension of the spring may be predetermined.

The hub 6 carries a pinion 6a which meshes with a countershaft gear 6b keyed to a pinion 20 6c which is rotatably mounted on a countershaft 6d and which meshes with a gear 6c secured to the main drive shaft 4.

The drive pulley 7 is driven from a suitable electric motor 25a through the medium of a 25 drive belt 25, and a means is provided for changing the speed of rotation of the drive pulley 7 at the will of the operator. This means consists in providing the motor 25a (Figs. 2, 33 and 34) with a drive pulley comprising two halves, one half 26 being fixed to the motor shaft 27 and the other half 28 being axially slidably on the half 26, a coil spring 29 being employed to urge the pulley half 28 toward the pulley half 26. The two pulley halves 26 and 28 are of frusto conical 35 shape and opposed to each other to provide a groove having tapered sides for the reception of the drive belt 25.

The electric motor is mounted on a base 30 which is fixed to a rotatable support 31 having 40 a gear sector 32 fixed thereto. The gear sector 32 is meshed with an axially fixed worm 33, and the worm is rotated by means of a shaft 34 which is in turn rotated by gearing 35 from a shaft 36 which projects through the side frame 1 of 45 the machine and which is provided with a hand wheel 37. By rotating the hand wheel 37 the electric motor 25a is caused to swing about the shaft 31 as an axis and thereby increase or decrease the distance between the centers of the 50 main drive shaft 4 and the motor shaft 27, thus tending to increase or decrease tension on the drive belt 25, and by so increasing or decreasing the tension on the belt 25 the belt and pulley spring 29 either causes a separation of the 55 pulley halves or a movement of the pulley halves toward each other as the case may be, thus changing the radial distance of the belt from the axis of the motor drive shaft 27. This, of course, will change the speed of the belt 25 and 60 provide for an increase or decrease in the speed of rotation of the main drive shaft 4 of the wrapping machine, as desired.

The wrapping material "A", such as suitable paper, or material such as regenerated cellulose, 65 is carried in the form of a roll 38 which is supported on suitable arms 39 carried by the side frames 1.

Referring to Figs. 1, 2, 5, 16 and 27, the wrapping material A is passed over an idling roller 70 40 to a material advancing mechanism mounted upon an adjustable carriage 41 (Figs. 5 and 21).

When it is desired to use a double thickness of wrapping material, such material "B", in the 75

form of a roll 367, is rotatably supported on arms 368 carried by the rear ends of the side frames 1. A reel 369 is also provided for supporting a narrow strip of paper "C" having advertising material thereon.

If desired, any suitable means may be provided for circulating a refrigerant or cold air through the centers of the wrapping material rolls so as to prevent softening of the waxed surfaces of the wrapping material and thereby minimize the accumulation of wax on the working parts of the machine.

The carriage 41 rotatably supports a shaft 52 to which a smoothing roll 42 of substantial diameter is secured. The roll 42 preferably is hollow, and if desired may be cooled by circulating cold air, cooling fluid, or a refrigerant therethrough to prevent wax on the surface of the wrapping material from becoming soft and causing, as previously described, the accumulation of wax on the working parts of the machine.

The carriage 41 also supports a pair of wrapping material advancing or feed rolls 43 which are journalled therein, the advancing rolls 43 having their axes in a common vertical plane, and an additional pair of wrapping material advancing rolls 44 adjacent the rolls 43 and also having their axes disposed in a common vertical plane. The wrapping material A is conducted over the smoothing roll 42 and gripped by the feed rolls 43, suitable guide plates 45 being disposed between the smoothing roll 42 and feed rolls 43 to prevent sagging of the wrapping material between these rolls. The upper feed rolls 43 and 44 are preferably of rubber having a metal core and the lower feed rolls 43 and 44 are preferably of metal whereby the wrapping material will be positively fed and will not slip during the feeding thereof.

The carriage 41 also carries the cutting means or knife blade 46, to be later described, the knife blade being disposed to operate intermittently and to move between the pairs of rollers 43 and 44 to sever the wrapping material. The lower feed rolls 43 and 44 are provided with small toothed gears 48 and 49, respectively, which are meshed with a common idler gear 50 so that when the gear 48 is driven by means of a drive gear 51 the gears 48 and 49 will be driven simultaneously and in the same direction. The upper rolls 43 and 44 are so positioned with respect to the lower rolls 43 and 44 that during the feeding of the wrapping material, the wrapping material will be gripped between the rolls of each pair and advanced toward the wrapping mechanism.

The rolls 43, at their ends opposite the gear 48, are provided with intermeshed pinions, and similarly the rolls 44 are provided with intermeshed pinions 49a so that the upper rolls 43 and 44 will be positively driven by the lower rolls 43 and 44. The forward rolls 44 are so geared to the rear rolls 43, or are of such diameter that they rotate at a slightly greater speed than the rear rolls 43, whereby the wrapping material extending between the pairs of rolls will be placed under tension in order to facilitate the operation of severing the wrapping material.

The shaft 52, which carries the smoothing roll 42, is journalled in the carriage 41, and this shaft carries a drive gear 53 which is meshed with the idler gear 51, the idler gear being meshed with roll gear 48. The shaft 52 is rotated by means of a reciprocating mechanism, which is so arranged to provide a continuous feed of the wrapping material to the wrapping mechanism ex-

cept for those momentary periods when the cutter blade 46 severs the wrapping material to provide a sheet of wrapping material of predetermined length, and which mechanism is also so arranged that the speed of advancement of the wrapping material is accelerated and decelerated, respectively, just after and just prior to the operation of the cutter blade 46, so as to avoid any sudden stopping of the wrapping material A being advanced to the wrapping mechanism.

The mechanism for rotating the shaft 52 is carried within a suitable housing 54 which is pivoted upon the shaft 52, as shown in Figs. 16, 17 and 21. Slidably mounted within the housing 54 is a reciprocable element 55 having a longitudinal opening 56 therein which receives the end of the shaft 52. The reciprocable element 55 is connected at its lower end with a crank arm 57 mounted on a drive shaft 58. The shaft 58 is provided with a sprocket 59 that is driven by means of a chain belt 60 from a sprocket 61 mounted on a sleeve 125, the sleeve 125 being rotatably supported on the main drive shaft 4 (Figs. 3 and 5). The reciprocable element 55 is provided at each side of the opening 56 with rack teeth 62 and 63 which mesh with pinions 64 and 65, respectively, the pinions 64 and 65 being mounted upon short shafts 66 and 67, respectively, which are carried by the housing 54. The shafts 66 and 67 also carry freely rotatable pinions 68 and 69, respectively, which mesh with a common pinion 70 secured to the shaft 52. A driving connection in the form of an overrunning clutch 71 is provided between the pinions 64 and 68, and a similar driving connection in the form of an overrunning clutch 72 is provided between the pinions 65 and 69. These overrunning clutch devices are preferably of the friction type, as indicated in Fig. 18, and so arranged that a driving connection is effected between the two pinions 65 and 69 or 64 and 68 only during the rotation of one of the pinions 64 or 65, as the case may be, in one direction. In other words, the clutch devices act as free wheeling units which effect the drive during only one direction of rotation. Also, the clutch devices 71 and 72 are opposed to each other so that the clutch device 71 provides a driving connection between the pinions 64 and 68 upon one direction of travel of the reciprocable element, and the clutch device 72 provides a driving connection between the pinions 65 and 69 during the travel of the reciprocable element 55 in the opposite direction, so that regardless of direction of travel of the reciprocable element 55, the shaft 52, and consequently the feed rolls 43 and 44, by means of the chain of gears described, will always be driven in the same direction. This same motion, however, can be accomplished by other devices acting in a similar manner, such as, for example, a ratchet and pawl device.

The cutter blade 46 is provided with a series of sharp cutting teeth 73, and is arranged to move vertically and upwardly between the pairs of feed rolls 43 and 44 through a slot provided in a suitable wrapping material support 74 (Fig. 27) disposed between the pairs of feed rolls 43 and 44, at the end of each stroke of the reciprocable element 55. That is, the cutter blade 46 severs the wrapping material at the time the crank 57 is at dead center when the reciprocable element changes from one direction of travel to the other, and thus at which time the feed rolls 43 and 44 are momentarily at rest. The cutter blade 46 is detachably mounted upon a vertically

reciprocable plate 75 (Figs. 22, 23 and 27) which is guided at its ends in slots 76 formed in the sides of the carriage 41. The plate is preferably provided with an electric heating element 77 which transmits heat to the cutter blade 46 to melt and thereby prevent the accumulation of wax on the cutter blade.

The plate 75 is secured to a bracket 78 which is pivotally connected with a rocker arm 79 securely mounted on a pivoted shaft 80, the shaft 80 being pivotally supported by the carriage 41. The shaft 80 is provided with a lever 81 which is connected by means of a downwardly extending connecting rod 82 with one end of a pivoted 15 double ended lever 83 (Fig. 23), a suitable coil spring 84 being employed to urge the connecting rod 82 upwardly and maintain the plate 75, which supports the cutter blade 46, in its downward position. The opposite end of the lever 83 20 is provided with a suitable cam surface or cam roller 85 which engages with a suitable cam 86 keyed to the rotatable hollow shaft 125. The cam 86 is cylindrical except for a small cam projection 87 which engages with the cam roller 85 25 and through the linkages described, causes the cutter blade 46 to travel upwardly between the pairs of rollers 43 and 44 and sever the wrapping material. The cam projection 87 is carried by a removable block 88 suitably secured to the cam 30 86 and is so arranged with respect to the crank arm 57 that it only engages with the cam roller 85 at the end of each stroke of the reciprocable element 55, i. e. when the crank arm 57 is at dead center.

Because of the use of the reciprocable element 55, which is actuated by a crank arm 57, it is thus seen that the advancement of the wrapping material is substantially continuous except for the momentary period that the reciprocable 40 element 55 changes from one direction of travel to the other, and at which time the cutter blade 46 severs the wrapping material. It is also seen that by using the reciprocable element 55 and the crank arm 57, the rate of travel of the wrapping 45 material is gradually increased after the severing operation and then is gradually decreased just prior to the next severing operation so as to prevent any sudden stoppage or sudden advancement of the wrapping material, and thus 50 avoid danger of tearing the wrapping material. The wrapping material feed means described above forms the subject matter of my copending application, Serial No. 27,144, filed June 18, 1935.

In order to provide for a change in length 55 of the sheet of wrapping material which is severed from the material advanced by the feeding rolls 43 and 44, the stroke of the reciprocable element 55 is made adjustable, and this is accomplished by adjusting the throw of the crank 60 arm 57. The crank arm 57 (Figs. 16, 19 and 20) is provided with grooved guideways 89 which 65 slidably receive a block 90. The block 90 carries the crank pin 91 to which the end of the reciprocable element 55 is pivoted, and is threaded 70 to receive an axially immovable adjusting screw 92 carried by the crank arm 57. The screw 92 is rotated within the crank arm by means of meshed gears 93, one of which is rotated by a suitable hand wheel 94 (Figs. 16 and 19). By 75 rotating the hand wheel 94 the block 90, which carries the crank pin 91, may be moved toward or away from the axis of the shaft 58 to decrease or increase the throw of the crank, as the case may be, and thus predetermine the degree of 75 rotation of the feed rolls, and thereby predeter-

mine the length of wrapping material to be advanced by these rolls.

If desired, the crank pin block 90 may be provided with an indexing finger 95 which may be set according to index marks 96 appearing on 5 the crank arm, which correspond with different lengths of the wrapping material.

In order to properly locate a sheet of wrapping material, advanced and severed from the source of supply over the station where wrapping of the 10 article is started, the carriage 41 is slidably and adjustably supported on suitable guides 97 carried by the side frames. Adjustment of the carriage 41 is obtained by means of screws 98 which are threaded into depending brackets 15 99 carried by the carriage and which are operated by means of suitable gearing 100 from a shaft 101 extending between the side frames 1, the shaft having a suitable hand wheel 102 arranged externally of one of the side frames which 20 can be turned to cause the carriage 41 to travel forwardly or rearwardly with respect to the wrapping mechanism, and thereby to serve as a means for properly locating the sheet or sheets 25 of wrapping material with respect to the article 25 to be wrapped. This movement also provides a means for locating the discharge position of the wrapping material whereby the overlapping position of the ends of the material with respect to the bottom of the article being wrapped can be 30 predetermined.

In order to compensate for the forward or rearward movement of the carriage 41 and prevent advancement or retardation of the wrapping material by the feed rolls 43 and 44 during this 35 movement of the carriage, the carriage is connected by linkages, including a bell crank lever 103 and links 104 and 105, with an arm 106 pivoted on the crank shaft 58 adjacent the sprocket 59. This arm 106 carries spaced idler rolls or sprockets 107 which engage with the opposite driving and return portions of the chain belt 60 so that upon movement of the shaft 52 with the carriage 41 with respect to the axis of the crank shaft 58, the arm 106, through the engagement of the 45 chain belt 60 with the idlers 107, will cause the crank shaft 58 to rotate an amount proportional to the distance traveled by the shaft 52, and thereby prevent rotation of the shaft 52 and the consequent rotation of the feed rolls 43 and 44, 50 thus preventing advancement of the wrapping material during adjustment of the carriage 41.

Referring to Figs. 5, 27 to 30, 56, 57, and 58, the wrapping material as it leaves the forward feed rolls 44 is fed to a mechanism which carries and supports the same up until the time the article, such as a loaf of bread "D", indicated in Fig. 58, is moved to its wrapping position. My copending application, Serial No. 25,097, filed June 5, 1935, includes the wrapping material positioning mechanism described herein. This mechanism includes forward and rearward spaced conveyor shafts 108 and 109, the axis of the forward shaft 108 being slightly above the plane of travel of the wrapping material between the feed 60 rolls 43 and 44, and the rearward shaft 109 being disposed some distance below the forward shaft 108 and near the rolls 44. The shafts 108 and 109 are provided with sprockets 110 which are arranged to carry spaced conveyor chains 111. 70 Suitable idlers 112 are provided slightly in advance of the vertical plane of the rearward shaft 109 to engage with the advancing and return portions of the chains 111. These conveyor chains 111 carry wrapping material supporting bars 113. 75

These bars or flights 113 are preferably covered with rubber to avoid the accumulation of wax and are arranged in pairs so that during the advancement of the wrapping material, one pair 5 acts to support and carry the sheet of material being advanced, and the succeeding pair acting to carry and support the next following sheet of wrapping material advanced.

Extending transversely of the side frames and 10 between the advancing and return portions of the conveyor, is a suitable guide element 114 which also supports the wrapping material being advanced, this guide element being slightly in advance of the vertical plane of the rearward shaft 15 109. The rearward shaft 109 is provided with a pinion 115 which is meshed with a gear 116 (Fig. 30 rotatably mounted upon a shaft 117, the gear 116 carrying a sprocket 118 which is driven by means of a chain belt 119 from a sprocket 120 which is carried by a short shaft 121. The shaft 121 is carried by a bracket 122 (Figs. 3 and 32) secured to one of the side frames 1. The shaft 121 is provided with a pinion 123 which is arranged to mesh with a Geneva gear 124, the Geneva gear being mounted on the sleeve 125 which is rotatably supported on the main drive shaft 4. The sleeve 125 carries a cam 126 (Figs. 3 and 13 to 15) which pivotally supports a clutch arm 127 having a catch shoulder 128 at one end and a cam surface 129 at the opposite end, the clutch shoulder 128 being engageable with a clutch element 130 rigidly secured to the main drive shaft 4 adjacent the cam 126. A coil spring 131 is employed to exert pressure against the arm 127, tending to throw the catch shoulder 128 into position to be engaged by the clutch element 130. A suitable adjustable stop means 132 is also provided to limit the movement of the catch shoulder 128 inwardly towards the axis of the drive shaft 4.

40 Disposed adjacent the cam 126 is a cam roller 133 which is arranged to be moved into the path of the cam portion 129 of the clutch arm 127 to prevent engagement of the clutch shoulder 128 with the clutch element 130 when no unwrapped articles are being fed to the machine, even though the main clutch described in connection with Figs. 10 and 11 is engaged. The roller 133 is carried on the end of a pivoted arm 134, which arm is pivoted on a pivot pin 135 carried by the lower cross member 2 of the main frame. This arm 134 is actuated by means of toggle levers 136, one of the levers being pivoted to the arm 134 and the other lever being pivoted to an adjustable bracket 137 carried by the cross piece 2. The latter lever is provided with a projecting portion 138 and a coil spring 139 extends between this projecting portion 138 and the supporting portion 140 on the bracket 137, which spring functions as a snap action spring to hold the roller 133 out of engagement with the cam portion 129 of the arm 127 when the toggle levers are in their retracted position, as indicated in Fig. 14. Normally, when no articles are being fed to the wrapping machine the cam roller 133 is in a position to engage with the cam portion 129 and hold the catch shoulder 128 out of the path of the rotating clutch element 130.

The toggle levers 136 are actuated by means of a rod 141 connected with a lever 142 pivoted to a shaft 143 which carries a lever 142a connected by means of a rod 144 to a pivoted lever 145 which is secured to a shaft 146. The shaft 146 is provided with a depending trip bar 147 75 which is arranged to be engaged by an unwrapped

article being fed into the wrapping machine, as will be later described in detail. The shaft 146 is provided with an arm 148 which is connected with one end of a coil spring 149 attached at its other end to the side frame, as shown in Fig. 6. The springs 139 and 149, when the toggle links 136 are in the position shown in Fig. 13, are substantially on dead center, so that when the trip bar 147 is engaged by the article being fed into the wrapping machine, 10 these springs 139 and 149 move from their dead center position and cause the linkage described to retract the toggle links 136 and move the cam roller 133 away from the cam portion 129 of the arm 127, so that the coil spring 131 moves the 15 arm 127 in such a manner that the catch shoulder 128 extends into the path of the clutch element 130. Then when the clutch element 130 engages the catch shoulder 128 this causes the sleeve 125 on the main shaft 4 to rotate, thus 20 driving the wrapping material feed rolls 43 and 44, cutter blade 46, and the wrapping material carrier.

In order to automatically reset the cam roller 133 in a position to be engaged by the cam portion 129 of the arm 127, the lower toggle lever 136 is connected by means of an adjustable rod 150 with a lever 151 which is pivoted intermediate its ends to the pivot pin 135, the free end of the lever 151 carrying a cam roller 152 which, 25 when the toggle levers are retracted, is disposed to be engaged by a cam surface 153 arranged on the cam 126, so that upon engagement of the cam roller 152 with the cam surface 153, the toggle levers 136 are moved back to the position indicated in Fig. 13. This action occurs after 30 each article is fed into the wrapping machine.

The Geneva gear 124 is of the type in which approximately one-half of the circumference is provided with gear teeth so that upon rotation of 40 the gear 124 by the rotation of the sleeve 125, as previously described, the conveyor comprising the chains 111 and cross bars 113 will move only a distance equal to one-half of the length of the conveyor chain upon each full revolution 45 of the gear 124.

The wrapping material A, as it is fed by the forward advancing rolls 44, hangs downwardly from the lower roll in a suspended position, as indicated in Fig. 56, between the side chains 50 111 of the carrier where, during the operation of the carrier, the under surface of the wrapping material is engaged by the first flight 113 of one pair of flights which are moving in an upward direction. This first flight 113 then raises the 55 wrapping material and carries it over the horizontal support 114 with the front edge of the wrapping material trailing the portion engaged by the first flight, as indicated in Fig. 56a. During the continued operation of the carrier the 60 pair of flights 113 carry the wrapping material to the position indicated in Fig. 57, the second flight 113 supporting the forward or leading end of the wrapping material and the first flight of 65 this pair of flights having moved beyond the leading edge of the wrapping material.

In order to assist the advancement of the wrapping material from the forward feed rolls 44 and to direct the same into a position to be engaged by the cross bars or flights 113 of the conveyor, 70 it is preferred to provide a hinged plate 154 having an edge which serves as a wiper for the lower feed roll 44 to prevent the accumulation of wax thereon, and also to prevent the wrapping material from curling about the lower roll 75

44 as the free end thereof moves between the feed rolls 44.

It is also desirable to provide an additional plate 155 hingedly carried by the rearward conveyor shaft 109 to extend into the path of the cross bars 113, as indicated in Fig. 27, and slightly below the plate 154, so that, as seen in Fig. 27, the wrapping material is positively directed into a position to be engaged by the cross bars 113 of the conveyor. As the cross bars 113 of the conveyor move during operation of the conveyor, they engage with the under side of the plate 155 and pivot the same until they clear the plate, as indicated in Fig. 29, thus carrying the wrapping material into its substantially horizontal position. Similarly, when the carriage 41 is moved into its forward adjusted position, the cross bars 113 may also engage with the pivoted plate 154 and raise the plate during operation to clear the same. In order to return the plate 155 to the position indicated in Fig. 27, it is preferred to employ a suitable tension spring 156, a suitable stop means 157 being provided to limit the return movement of the plate 155.

It is also desirable, in the case of the upper forward feed roll 44, to provide a means for preventing the wrapping material from adhering to or curling about this roll. This is accomplished by forming the upper roll 44 with circumferential grooves 158 and providing substantially U-shaped guards 159 which are located in these grooves, and have their ends secured to the carriage 41 above the axis of the roll, which will then prevent the wrapping material from adhering to the roll.

It is also preferred to provide means in the form of a scraper plate 154a (Fig. 27) adjacent the lower feed roll 43 for scraping any wax that may have accumulated thereon during the operation of advancing the wrapping material.

The articles to be wrapped are fed into the machine by means of an endless conveyor which includes side chains 160 operating over sprockets 160a mounted on shafts 160b, the latter being journaled on side elements 160c. The rearward shaft 160b is provided with a pinion 160d meshed with gear 160e, the gear 160c being mounted on a shaft 160f provided with a sprocket 160g. The sprocket 160g is driven by means of a chain belt 161 from a sprocket 162 carried by the main drive shaft 4, as shown in Figs. 3 and 5. The article to be wrapped is fed from the table 163 of the infeed conveyor onto an elevating table 164 (Figs. 5 to 8), which table is pivoted by means of pivot pin 165 to a swingable arm 166. The arm 166 is carried by two levers 167 and 168 pivoted thereto. The lever 168 is pivoted at one end to the arm 166, and at its opposite end to a shaft 169 carried by the side frames. The lever 167 is considerably longer than the lever 168 and is pivoted, by means of a pivot pin 170, to the lower cross member 2 and is provided with an angular extension 171 which carries a cam roller 172 which engages with an internal cam surface 173 provided in the cam 126 previously described, so that during rotation of the cam 126 the elevating table 164 will be caused to swing through a curved path adjacent a curved guide plate or backstop 174 to the position indicated in Figs. 2 and 37. The elevating table 164 is provided with a pair of spaced, adjustably mounted, side guides 175, as shown in Figs. 6 and 8, which are disposed to receive the unwrapped article between the same

from the infeed conveyor, the infeed conveyor being provided with spaced side guides 176 having extensions 177 pivoted thereto which overlie the elevating table 164. The extensions 177 are arranged to swing upwardly as the table 164 moves upwardly, and the side guides 175 are arranged in such a manner that when the table 164 reaches its uppermost position, as indicated in Fig. 2, they move downwardly to the dotted position shown in Fig. 8, to permit the operation of other portions of the wrapping mechanism. This is accomplished by arranging the guides 175 in a slidable manner through slots 164a (Fig. 7) in the elevating table 164 and forming the same with projecting portions 178 which receive a pivoted bar 179. The bar 179 and the projections 178 are so arranged that they engage a stop when the table 164 nearly reaches its uppermost position, which causes the bar 179 to prevent further upward movement of the guides 175 during the remainder of the upward movement of the table 164. Also, a stop means 180 is provided on the guide 174 which functions, when the elevating table 164 nearly reaches the bottom of its stroke, to again move the guides 175 to the position shown in solid outline in Fig. 8.

The supporting portions 175a of the guides 175 are mounted on the oppositely threaded ends of an adjusting screw 175b, which is provided with a crank or adjusting handle 175c which crank can be rotated to permit adjustment of the distance between the guides 175.

It will be noted in Fig. 5 that the article elevating table 164, when it is in its lowermost article receiving position, is inclined downwardly and rearwardly from its forward edge. In the wrapping of sliced bread, for example, some of the slices may be slightly displaced with respect to the other slices, and also the top surface may be covered with crumbs which have accumulated during the slicing of the bread. I have found by inclining the elevating table, as described, that when the sliced bread is discharged onto the table 164 it will have sufficient momentum when it engages the backstop 174 to cause or tend to cause the displaced slices to be shifted to their proper relative positions. Also, any crumbs which may have been on top of the sliced loaf will be thrown over against the backstop 174, so that during the upward travel of the loaf they will be released.

In the case of wrapping an article, such as sliced bread, it may be desirable to provide an intermittently operating element such as a horizontal bar 370 (Fig. 5) which, during the upward travel of the elevator table 164, quickly swings toward the loaf of sliced bread carried by the elevator table and strikes the same to move any slices that may have shifted laterally with respect to the loaf, into their proper relative positions. The bar 370 may be carried by a pair of bell crank levers 371 which are pivoted to the side frames 1, one of which is connected by a rod 372 with a lever 373 having its lower end pivoted to shaft 169. The lever 373, as here shown, is provided with a cam surface 374 which engages with a rotatable cam 375, the cam 375 being carried on the hub of the infeed conveyor drive gear 160e (Figs. 4 and 5). A coil spring 376 is employed to hold the lever 373 in engagement with the cam 375 which cam is timed to allow the bar 370 to quickly strike the sliced loaf and move back to its normal position out of the path of the elevator table 164.

The elevating table 164 moves the bread or other article to be wrapped upwardly to the position indicated in Fig. 2, carrying with it the sheet of wrapping material which has been severed by 5 the knife blade 46 and discharged from the forward feed rolls 44, the wrapping material then hanging down at each side of the article to be wrapped, the article and the suspended wrapping material moving upwardly between a pair of side 10 gripper plates 181 and 182 which engage the sides of the article and hold the wrapping material against the same, suitable swingable stop members 183 being employed to engage with the top of the article which has been moved up to this 15 position.

It will be noted that when the elevator table 164 is in its uppermost position, as shown in Figs. 2 and 37, the wrapping material A is draped over the top of the article with the rear end hanging 20 down along the rear side of the elevator table 164 and with the front end positioned on the table 164. In order to facilitate the wrapping of the article and to properly locate the wrapping material, it is preferred to provide a cross bar 371 which extends between a pair of arms 378, the arms being slidably mounted in adjustable members 379 pivoted to the side frames 1, spring means 377a being employed to hold the bar in its normal position. This bar 371 is disposed in 25 the path of movement of the elevator table 164 but above the wrapping material supported by the carrier flights 133 so that during the upward movement of the elevator table 164 the forward portion of the wrapping material is 30 caused to lie relatively close to the forward side of the article being elevated into wrapping position. As the table 164 is retracted to its lowermost position the bar 371, through the action of the spring means 377a and by gravity, moves 35 downwardly to the position indicated in Fig. 35 out of the path of parts of the wrapping mechanism, where further movement is prevented by a suitable stop 380.

Also, as the article approaches its uppermost 40 and wrapping position, end gripper plates 184, preferably faced with rubber to prevent wax from accumulating thereon, are actuated to engage with the projecting sides of the wrapping material and bring the same into engagement in 45 gripping relation with the ends of the article, to form the first or upper end folds at the end of the article, as indicated in Fig. 59. These end gripper plates 184 (Figs. 39 and 39a) are adjustably mounted upon brackets 185 carried by shaft 50 portions 186 which are journaled in arms 187, the arms 187 being slidably supported on a pivoted shaft 188. The arms 187 are provided with recesses 189 (Figs. 6 and 39a) and the shaft portions 186 project through the arms 187 into 55 the recesses 189, and are provided with levers 190 having cam rollers 191 thereon, which levers 190 function to swing the plates 184 toward and away from each other in such a manner that when they swing toward each other they engage 60 with the projecting end portions of the wrapping material and bring such end portions into engagement with the ends of the article, thereby forming the first or top end folds. The levers 190 are provided with adjustable screws 190a which 65 are disposed to engage with the arms 187 and limit the outward movement of the plates 184. Also, coil springs 192 are disposed about arms 187 and have their ends secured in any suitable manner to the arms 187 and to the shaft portions 70 186 so that the torsion in such springs continu-

ously tends to urge the plates 184 to their outward positions.

The cam rollers 191 are actuated by cams 193 mounted on a cam shaft 194 extending between the side frames. This cam shaft 194 (Figs. 3, 4 and 5) is provided with a sprocket 194a which is driven by means of a chain belt 195 from a sprocket 196 carried by the main drive shaft 4 and the cam shaft 194 is driven at the same speed as and synchronized with the drive shaft 10 4. Also, the arms 187 are arranged for a vertical movement, such as indicated in Fig. 5. This is accomplished by pivoting the shaft 188 which is journaled in a supporting member 200 which extends downwardly from the upper cross member 15 3, through the medium of a lever 197 which is connected by means of a link 198 with an arm 199 which is pivoted at one end to the link 198 and at its opposite end to the supporting member 200. The arm 199 is provided, intermediate 20 its ends, with a cam roller 201 which is disposed to engage with a cam 202, the cam 202 being carried by the cam shaft 194. The cams 193 and 202 are so arranged that each time an article is 25 moved to its wrapping position, the plates 184 are moved inwardly to grip the ends of the article, and so that after a predetermined length of time, during which time certain of the wrapping operations are performed, the arms 187 swing upwardly to the position indicated in Fig. 30 5 so that the plates 184 clear the article being wrapped to permit the partially wrapped article to move forwardly for the performance of other wrapping operations.

In order to provide for the wrapping of articles 35 of different lengths, the arms 187 are slidable on the pivoted shaft 188 but are rotatably fixed thereon and are provided with oppositely threaded parts 203 which threadedly receive a screw member 204 having right and left hand threads at its 40 opposite ends, the screw member 204 being provided with a hand wheel 205 for rotating the screw and thereby adjusting the arms inwardly and outwardly with respect to each other. In 45 order to wrap articles of different widths and provide the proper upper end folds, it may be desirable to provide the shaft portions 186 with interchangeable gripper plates 184 which are of the proper width for the article being wrapped. The end grippers 184 and side grippers 181 and 50 182 engage the article with sufficient endwise and transverse pressure to hold it in a suspended manner after elevator table moves to its lower article receiving position.

As indicated in Fig. 60, the rear end fold 206 55 and the rear bottom fold 207 are formed after the formation of the top end fold 208, and the folds 206 and 207 are performed at substantially the same time. However, the bottom fold 207 is started slightly in advance of the rear end fold 60 206. Prior to the formation of the rear end fold 206 and bottom fold 207, the elevating table 164 has started its downward movement, leaving the partially wrapped article suspended by means of the side gripper plates 181 and 182 and the 65 end gripper plates 184, as indicated in Fig. 59. The forward side gripper plate 182 just prior to the downward movement of the table 164 moves the article slightly rearwardly against the gripper plate 181 and over a bar 182a carried by the 70 carriage 209 which now will be described. The bar 182a assists in holding the article as shown in Fig. 59 after the elevator table moves to its lower position. This is particularly advantageous in the wrapping of sliced bread, as the slices will 75

be more firmly held in contiguous relation. The mechanism for forming the folds 206 and 207 is movable transversely of the article being wrapped and includes a carriage 209 which is supported by means of side portions 210 having outwardly extending rollers 211 thereon, which are guided in suitable guides 212 attached to the side frames. The carriage 209 is provided with a plurality of rollers 213 which extend between the forward ends of the portions 210 and which are freely journaled therein, the rollers 213 forming the means which provides the rear bottom fold 207. The carriage 209 supports an axially fixed rotatable screw member 214 having oppositely threaded ends which threadably receive brackets 215, on which side plates 216 are mounted for providing the end folds 206, and being slidably horizontally relative to the supporting brackets 215.

20 Movement of the side plates 216 relative to the brackets 215 is obtained by providing the brackets 215 with slots 211 and providing cover members 218 which are connected to the side plates 216 by securing members or bolts 219 extending through the slots 211, a separator key 219a being positioned in the slot 211 between the plate 216 and the cover plate 218, and the bolts 219 extend through the separator key 219a.

The carriage 209 is moved forwardly and rearwardly by a pair of levers 220 which are keyed at their upper ends to a shaft 221 and which are connected by means of links 222 to the carriage 209, the links 222 being connected to the carriage 209 by means of pivot pins 223 and being connected to levers 220 by means of pivot pins 224. The shaft 221 is journaled in the side frames and provided with a pivoted arm 225 having a cam roller 226 at its free end, which is arranged to be engaged with a cam 227 carried by the cam shaft 194. The arm 225 is provided with an eye-bolt 226a which extends through an opening 226b in one of the levers 220 and provided with a stop collar 226c at its outer end, a coil spring 228 being provided between the stop collar 226a and the lever 220, thus providing a means for applying a yielding pressure to the lever 220 in a forward direction. The arm 225 is provided with a shoulder 229, which normally contacts with a shoulder 230 formed on the lever 220.

50 In order to adjust the length of travel of the carriage 209 to provide for the wrapping of articles of different widths, the shaft 221 (Figs. 3 and 52) is provided with an L-shaped arm 231 which is rigidly secured thereto and which is provided with an adjustable shoe 232 having a curved cam surface 233, the shoe being pivoted at one end to the free end of the arm 231 and is provided with an externally threaded yoke 234 which receives a threaded socket 235, which encloses the head of a micrometer screw 236. The screw 236 is threaded through a nut 237 which is pivoted on the arm 231 so that upon rotation of the screw 236 in the nut 237 the shoe 232 may be pivoted about its axis 238. Means comprising a slot 239 in the arm 231 and a locking stud 240, is provided for securing the shoe 232 in the desired adjusted position. The cam surface 233 of the shoe 232 is disposed to be engaged by a cam roller 241 which is carried by a cam member 242 rigidly secured to the cam shaft 194. During a forward movement of the lever 220, produced by the rotation of the cam 227, the cam surface 233 is engaged by the cam roller 241 which, being secured through the L-shaped arm 231 to the shaft 221, limits the forward movement of the

levers 220, at which time the coil spring 228 may yield and thereby permit the main driving roller 226 for the levers 220 to follow its path in the cam 227.

As previously stated, the side plates 216, which form the rear end folds in the wrapper, are slideable relative to the carriage 209. This sliding movement is provided by means of a cam 243 mounted on the cam shaft 194 having a cam follower 244 mounted upon the end of a lever 245 which is pivoted intermediate its ends to one of the depending levers 220 by means of a pivot pin 246. The end of the arm 245 opposite the end to which the follower 244 is secured, or lower end, as seen in Figs. 44 and 47, is bifurcated at 247 to receive a pin 248.

The cover plates 218 are provided with pivot studs 249 which pivotally support actuating links 250 which are pivotally connected by pivot studs 251 to the ends of levers 252, the levers being pivoted intermediate their ends by means of pivot studs 253 to the plate supporting brackets 215. The ends of the levers 252 opposite the studs 251 are pivoted by means of pivot studs 254 to links 255 which are slidably mounted upon a cross bar 256 (Fig. 48), the cross bar 256 being provided with arms 257 which are pivoted on the pins 224 which connect the levers 220 with the links 222. One of the arms 257 carries the pin 248, previously described, which is received by the bifurcated end 247 of the pivoted lever 245. Inasmuch as the links 255 are slidably disposed upon the cross bar 256, it will be noted that such links will permit of the free adjustment of the brackets 215 by means of the adjusting screws 214. Each of the rollers 213 is provided with a small gear 213a which meshes with a slidable rack 258 which is guided on one of the side frames by means of a bracket 259. The rack 258 provides for an independent rotation of the rollers 213, as will be later described. The rack is slotted at its rearward end to provide a recess 260 for receiving the lower end 261 of an actuating lever 262 which is pivoted intermediate its ends to the side frame on the pivot stud 263. The upper end 264 of the lever 262 is provided with a cam roller 265 which is actuated by a cam 266 mounted on the cam shaft 194.

During the operation of forming the end fold 206 and bottom fold 207, the carriage 209 is moved forwardly by the levers 220 and the rollers 213 engage with the depending rear portion of the wrapping material, as seen in Figs. 59 and 60, and fold or carry this depending portion of wrapping material upwardly against the bottom of the article which is suspended by means of the side gripper plates 181 and 182 and the end gripper plates 184, and during this operation the rollers 213 move, by reason of the meshed engagement of the gears 213a with the rack 258, relative to the rack, thereby producing a rotation of the rollers during a forward movement, which tends to smooth out the wrapping material as it is brought into engagement with the bottom of the article. Also, as the carriage 209 approaches the end of its forward stroke, the rack 258 moves rearwardly, continuing the rotation of the rolls 213, to eliminate the possibility of the bottom fold of wrapping material from moving rearwardly of the article as the partially wrapped article is being propelled forwardly for the next operation, which forward movement, as will be later described, occurs before the carriage 209 begins its return stroke.

In Fig. 81 I have shown a modified construc-

tion in which the rollers are replaced by a relatively small roller 381 arranged at the extreme forward ends of the portions 210 of the carriage 209 and a second roller 382 spaced rearwardly 5 therefrom, which rollers carry an endless belt 383 of canvas or other suitable material. The roller 382 is provided with a suitable pinion such as one of the pinions 213a, previously described, which meshes with the reciprocable rack 258. The 10 action of the belt or apron 383 is similar to the action of the rollers 213. However, in this modified construction the carriage may be adjusted to move forwardly just before the elevator table commences its downward stroke, to provide a 15 partial support for the article through engagement of the apron 383 with the rear corner of the article as the elevator table 164 moves away from the article.

Also, slightly after the rollers 213 first engage 20 with the wrapping material to form the bottom fold 207, the side plates 216 begin to move forwardly and engage the rear portions of the wrapping material which projects beyond the end of the article, and these side plates 216, during 25 their continued forward movement, fold these projecting portions of the wrapping material inwardly toward the ends of the article being wrapped, but over the end gripper plates 184. The end gripper plates 184, after the formation 30 of the rear end folds 206, then move vertically to clear the rear end folds 206, as previously described and then swing outwardly.

Referring to Figs. 49, 50 and 51, the side plates 216, which form the rear end fold, are practically vertical for the major portion of their height but are formed with an inclined portion 267 along their lower edges so as to fold and crease the wrapping material closely against the bottom edge of the article being wrapped. Also, 40 the forward edges of the plates are inclined downwardly and rearwardly so that the folding operation begins at the top and is gradually completed towards the bottom of the article as the side plates 216 move forwardly. Also, substantially at the region of connection of the inclined portion 267 with the main portion of the plate 216, the plate is formed with an outwardly extending flange 268 which, as shown in Figs. 49 and 51, serves to roll a portion of the projecting 45 wrapping material over the horizontally projecting portion of the wrapping material substantially at the start of the rear end folding operation. Furthermore, the edge of the inclined portion 267 is so arranged that as the side plate 50 moves forwardly, it creases the folded-over portion, represented by the letter H in Fig. 51, which has been formed by the outwardly extending flange 268, thus providing a means whereby 55 a substantially square and smooth corner may be obtained.

A suitable wrapping material tensioning mechanism is provided for smoothing out the wrapping material as it is being moved to the 60 position indicated in Figs. 57 and 58. This mechanism, as shown in Figs. 6, 35, 36, 37, and 38, cooperates with the wrapping material carrier, previously described, and includes a pair of levers 269 which are pivoted to brackets 270 mounted upon the guides 212. Pivoted at 276 to these levers 269, above their pivotal axes, are a pair of L-shaped levers 272 having an interconnecting rod 273 at the ends of the shorter legs 274 thereof, the end portions of the shorter legs 274 being provided with cam surfaces 275 which

cam surfaces are disposable, during a movement of the pivotal levers 272, about their pivotal axes 276 in the path of the cross bars 113 of the wrapping material carrier conveyor, as indicated in Fig. 35. 5

The upper ends of the levers 269 are connected with the upper ends of the levers 272 by means of coil springs 277 which tend to draw the upper ends of these levers toward each other. Also, the levers 269 are urged to pivot in a clockwise direction by means of coil springs 278 which are connected at one end to the side frames at 279 and at their opposite ends at 280 above the pivotal axes of the levers 269. The tendency of the levers to be moved in a clockwise direction is 10 limited by means of lugs 281 carried by the levers 272, which are disposed to engage with stop pins 282, carried by the supporting structure for the wrapping material carrier conveyor. The maximum rearward position of the shorter legs 274 15 of the levers 272 is indicated in Fig. 35, in which position the lugs 281 are in engagement with the stop pins 282. The levers 272 are provided with projecting arms 283 between the legs 274 and their pivotal axes 280, which arms are provided 20 with rollers 284. The upper ends of the levers 269 are provided with rearwardly extending rods 285 having adjustable stops 286 at their rearward ends. These rods are slidably disposed in pivot studs 287 carried by L-shaped brackets 288 25 which are attached to the carriage 209. These brackets are provided with cam surfaces 289 which are engageable at predetermined times with the rollers 284 carried by the previously described arms 283. 30 35

During the operation of the tensioning mechanism, the wrapping material, as it is being carried forwardly by one of the moving cross bars 113 of the wrapping material carrier, is engaged by the rod 273 (Fig. 35) which extends between 40 the levers 272, so that during the continued movement of the cross bar 113 the wrapping material is firmly held under yieldable tension to keep the same smooth, and also during the continued forward movement of the cross bar 45 113 the levers 272 are pivoted about their pivotal axes 276 to the position substantially as shown in Fig. 37, thereby increasing the distance between the upper ends of the levers 272 and 269, and thus increasing the tension in the springs 50 277. 55

In this position, the carriage 209 is in its rear-most position and the article to be wrapped is moved forwardly, as previously described, to its wrapping position, as shown in Fig. 37. Then 60 after the elevating table 164 moves downwardly into a position to receive another article, and as the carriage 209 moves forwardly during the operation of forming the bottom fold 207, the tension of the springs 278, since the pivot studs 287 move away from the stops 286 on the rods 285, tends to rotate the levers 269 about their axes in a clockwise direction. During this period the cross bar 113, which has been in engagement 65 with the cam surface 275 of the levers 272, has moved the lever 272 in a counterclockwise direction and released the wrapping material. Thus, the rod 273 clears the cross bar 113 with which it was engaged in moving the wrapping material to the wrapping station and moves, by reason of 70 springs 277, back to a position to be engaged by one of the cross bars 113 carrying a succeeding sheet of wrapping material to the wrapping station. During this movement the rollers 284 on the arms 283 engage the cam surfaces 289 to 75

prevent engagement of the rods 273 with the forward smoothing roll 213.

As the elevator table 164 moves downwardly the bar 377, as shown in Figs. 36 and 37, drops to its lower position in the path of movement of the carriage 209, so that it will yieldably hold the forward downwardly projecting end of the wrapping material against the front smoothing roller 213 when the carriage 209 moves forwardly, the 5 spring holding bar 377 moving forwardly with the carriage 209 for a portion of its travel. This bar 377 yieldably holds the wrapping material under tension as the partially wrapped article is moved forwardly under the heater bottom plate 290 to 10 complete the operation, whereby to snugly confine the wrapping material about the article.

The forward movement of the partially wrapped article under the heater plate 290 gradually withdraws the depending portion of wrapping 20 material from between the bar 377 and forward roller 213 to actually start the formation of the 25 front bottom fold, which is completed as the article is moved completely onto the heater bottom plate 290.

After the rear end fold 206 and the bottom fold 207 have been formed, the partially wrapped 30 article is then moved forwardly onto the heater plate 290 where the bottom lap 291, front end folds 292 and bottom end folds 293 are formed 35 and the wrapper sealed, the heater plate 290 being substantially in the plane of the upper surfaces of the rollers 213.

As previously stated, the wrapping operations thus described are formed while the article is suspended by means of the end gripper plates 184 and the side gripper plates 181 and 182, and the article is moved forwardly onto the heater plate 290 by means of the side gripper plate 181. The side gripper plates are preferably provided with 40 longitudinal ribs 426 which tend to smooth out the wrapping material as the article and wrapping material is moved upwardly between the side gripper plates.

The mechanism for providing this movement 45 of the partially wrapped article by the side gripper plates 181 and 182 is shown in Figs. 4, 5, 40, 41, 42, and 43. This mechanism is supported by the depending sub frame 200 and is actuated by means of the cam surfaces 294 of the cam 50 member 242. The sub frame 200 is provided with a channel shaped guide element 295 extending longitudinally of the wrapping machine and disposed approximately along the center line of the wrapping machine. The channel shaped guide member 295 slidably receives a slide 296, the guide member 295 having a longitudinally extending key 297 disposed to extend into the recess 298 provided in the slide 296, as shown in Fig. 42. This slide 296 is provided with rack teeth 299 which mesh with a gear 300 mounted on shaft 301 carried in the sub frame member 200 and which carries a pinion 302. The pinion 302 meshes with a tooth segment 303 formed on a pivoted arm 304, the arm 304 being pivoted by means of a pivot 60 pin 305 to the sub frame 200. The arm 304 is provided intermediate its ends with a cam follower 306 which engages with the cam surface 294 which engages with the cam member 242, so that upon rotation of the cam member 242 the rocking motion of the arm 304, through the medium of the gears 300 and 302 and the rack teeth 299, causes the slide 296 to reciprocate within the guide member 295. The supporting leg 307 for the rearward side gripper plate 181 is rigidly 65 secured to the slide 296, and the side gripper

plate 181 is removably secured by means of nuts 308 to a holder 309 which is pivoted by means of pin 310 to the lower end of the supporting leg 307, the holder 309 being urged from the leg 301 by means of a coil spring 311, a suitable stud 312 being carried by the holder 309 and extending through the leg 307 to limit the hinging movement of the plate 181. The forward plate is hinged 15 connected to a forward depending leg 313 in the same manner as the plate 181 and the forward leg 313 is keyed to a short shaft 314 (Fig. 41) which is carried by an arm 315 which in turn is slidably mounted upon the slide 296 by means of the dovetailed ways 316. The arm 315 is provided with an internally threaded portion which threadably receives an adjusting screw 317, the adjusting screw being mounted on the end of the slide 296 for rotational movement only and having a suitable handle 318 for rotating the same. 20

The short shaft 314 also carries an arm 319 having a cam roller 320 at its free end, the cam roller 320 being disposed to travel in a stationary track 321 carried by the sub frame 200, the track being so shaped that upon forward movement of the slide the cam roller 320 will raise the forward side gripper plate 182 to a position such as that indicated in Fig. 5, whereby the partially wrapped article may be delivered on the heater plate 290 below the gripper plate 182 without interference 30 therewith. The mechanism for actuating the gripper plates 181 and 182 is so timed with respect to the operation of the carriage 209 that at approximately the time the carriage 209 completes its forward stroke, the slide 296 will cause the gripper plates 181 and 182 to bodily move the partially wrapped article onto the heater plate 290 and between the heater side plates 324, where the remainder of the wrapping operation is completed, at which time the forward side gripper 35 plate 182 starts to raise by reason of the roller 320 following along the track 321 in such a manner that when the slide 296 moves rearwardly the forward gripper plate 182 travels in a rearward direction and will clear the wrapped article. 40

The heater comprises the bottom heater plate 290 and side members 323 having the heater side plates 324 secured thereto. The bottom heater plate 290 is supported upon the heating elements 325 which are yieldably supported by means of 50 coil springs 326 upon a frame 327, the frame 327 being supported upon the side frame structure of the wrapping machine.

The members 323 are channel shaped and are supported upon brackets 328 which are guided 55 for adjustment inwardly toward and outwardly away from each other over the bottom heater plate 290, and which are arranged to be moved in this manner by means of a shaft 329 having oppositely threaded ends which carry the brackets 328. The shaft 329 is supported by the side frames 1 and provided with a hand wheel 330 which may be rotated to cause inward or outward movement of the side members 323 with respect to each other. The heater side plates 324 60 are removably carried by the side members 323 and the heating elements 331 are pressed, by means of the springs 332, against the heater side plates 324. 65

The rearward ends of the heater side plates 70 324 are formed with a side opening 333, the lower side of the opening having a surface 334 which slopes gradually upward and forward from the surface of the bottom heater plate 290, as shown in Figs. 65 and 68, the heater plates having por- 75

tions 335 extending into recesses 336 formed in the bottom heater plate, so that the curved surface 334 terminates below the surface of the heater plate 290. Pivotally secured to the sides 5 of the rearward portions of the heater side plates, are creaser plates 337 which are inclined so as to extend through the opening 333 at an angle and have their forward ends normally bearing against the surface of the bottom heater plate 290. A slight distance inwardly of the planes of the heater side plates 324, as shown in Fig. 69, coil springs 338 being employed to yieldably hold the forward corners of the creaser plates 337 in yielding contact with the surface of the bottom 10 heater plate. The creaser plates 337 are pivoted on studs 384, coil springs 385 being interposed between the heads of the studs and creaser plates.

As previously explained, the side gripper plates 181 and 182 move the partially wrapped article 20 onto the heater plate 290 between the heater side plates 324, and in so doing, the depending forward portion 291 of the wrapping material is engaged by the rearward edge 339 of the bottom heater plate 290 and folded upwardly to engage 25 with the bottom fold 207. Then as the article is moved forwardly by the gripper plates 181 and 182 the portions of the wrapping material which project beyond the ends of the article are engaged by the rearward edges of the heater side plates 324, as indicated in Fig. 62, which, during further movement of the article, fold these projecting portions of the wrapping material inwardly against the rear end folds 206 to form the front end folds 292, shown in Fig. 62.

30 During the formation of the front end folds 292 the remaining lower portions of the wrapping material which project beyond the ends of the partially wrapped article at the bottom thereof, travel below the creaser plates 337 while 35 projecting through the openings 333, so that as the article is moved further along the bottom heater plate the curved surfaces 334 engage with these projecting portions of the wrapping material and gradually fold the same into contact 40 with the previously formed front end folds 292 to provide the bottom end folds 293, indicated in Fig. 64, thus completing the wrapping operation.

As the end folds 293 are completed, the side gripper plates 181 and 182 reach the end of their 45 forward stroke and then travel rearwardly to engage with the next following article to be wrapped. The wrapped article remains between the heater side plates 324, during which time the heater plates provide for sealing the contacting 50 portions of the overlapping wrapping material, and is then moved forwardly by the following wrapped articles to the mechanism which cools the sealed portions of the wrapper.

The surfaces of the heater side plates 324 and 55 the heater bottom plate 290 are preferably formed with a series of spaced ribs or teeth 340 which function to apply heat to the wrapping material at spaced intervals and avoid the application of excessive heat. The heater side plates 324 are 60 preferably provided with flat springs 425 which grip the ends of the wrapped article as it is moved between the side plates by the side grippers and thereby prevent any tendency of the article to move rearwardly when the grippers 65 are retracted.

I have shown in connection with the heater a means for rapidly cooling the overlapping portions of the sealed folds of the wrapping material, which includes the circulation of the refrigerant 70 adjacent the portions that contact with the sealed

5 folds, which permits the use of relatively low temperatures for quickly chilling the heated waxed surfaces of the folds of the wrapper. This means includes a number of endless bottom belts 341 and spaced side belts 342 all of which are preferably of a thin metal such as copper. The bottom belts 341 operate over spaced front and rear pulleys 343 which are mounted on shafts 344 journalled in the side frames 1. The rearmost shaft 344 is driven by means of a sprocket 10 345 through the medium of a chain belt 346 from a sprocket 347 mounted on shaft 160f (Fig. 4). It is to be noted here that the bottom heater plate 290 extends up to the rearmost ends of the belts 341 (Fig. 77) and is disposed a slight distance below the plane of the conveying side of belts 341. Each of the vertical side belts 342 is spaced slightly above the belts 341 and operates from vertical pulleys 351 which are arranged in such a manner that the side belts 342 are offset 20 rearwardly of the bottom belts 341, as indicated in Fig. 77, so that the side belts 342, therefore, extend over the heater bottom plate 290.

The side belts 342 are movable toward and away from each other to compensate for different 25 lengths of articles being wrapped, and in order to provide this movement a horizontal support 352 is provided at each side of the mechanism. This support is provided with front and rear depending members 353 and 354, respectively, 30 the front member having an internally threaded bracket 355 and the rear member 354 having an internally threaded bracket 356. The brackets 355 of the two forward supports 352 are carried by the oppositely threaded ends of a screw or rod 357. Similarly, the brackets 356 are carried by the oppositely threaded ends of a screw 358. The screws 357 and 358 are provided with sprockets 358a which carry a connecting drive chain 359 and a screw 358 is provided with a hand wheel 40 360. By rotating the hand wheel 360 the supports 352 can, therefore, be moved relative to each other to adjust the relative positions of the side belts 342.

The rearward pulley 351 for each side belt is 45 keyed to a vertical shaft 361 which is journalled in the support 352 and bracket 356. The forward pulley 351 for each side belt is rotatably mounted on a spindle supporting arm 362 which is pivoted to a bracket 363, a set screw 363a being 50 provided in the bracket 363 for adjusting the position of arm 362. The bracket 363 carries a rigid member 364 having screw threads thereon, which member extends through a support 365 carried by the supporting member 352, nuts 366 55 being threaded on the screw threads at opposite sides of the support 365 so as to provide for longitudinal movement of the member 364 whereby the proper tension of the side belt 342 can be obtained.

The vertical shafts 361 of the rear pulleys 351 are each provided at their lower ends with a bevel gear 386a which meshes with a similar gear 386 mounted on a shaft 387 carried by the bracket 356 (Figs. 77 and 79). The shaft 387 has a pinion 388 which meshes with a relatively wide gear 389 rigidly secured to shaft 390 which is journalled in the side frames 1. The shaft 390 carries a pinion 391 which meshes with a gear 392 rigidly secured to the rear shaft 344 (Figs. 72 and 73), thus providing means for simultaneously driving the bottom and side belts 341 and 342, respectively. The side belts 342 are arranged to have substantial sliding contact with chambered heat absorbing elements 393 carried by the sup- 75

ports 382 (Figs. 77 and 78) and similarly the bottom belts 341 are arranged to have substantial sliding contact with a chambered heat absorbing element 394 carried by the side frames 1 and 5 which, in order to facilitate removal of the bottom belts, may be comprised of two separate chambers (a) and (b) (Figs. 76, 77 and 78). Each element 393, as shown in Fig. 80, is provided with an inlet and an outlet 395 and 396, respectively, 10 and the chambers (a) and (b) are each provided with an inlet 397 and an outlet 398, the outlet 398 of chamber (a) being connected by a conduit 399 with the inlet 395 of one side element 393 and the outlet of chamber (b) being connected by a conduit 400 with inlet 395 of the other side element 393.

A suitable mechanical refrigerating unit is employed for circulating refrigerant through the chambered elements 393 and 394 which includes 20 a compressor 401 and condenser 402 diagrammatically shown in Fig. 80, the condenser 402 being connected by a high pressure conduit 403 with the inlets 398 of the bottom heat absorbing elements 394a and 394b. The refrigerant is returned through conduit 404, which is in communication with the outlets 396 of the side heat absorbing elements 393, to the suction or low pressure side of the compressor 401.

By using a cooling device of the type mentioned, 30 the belts 341 and 342, through contact with the heat absorbing elements described, can be cooled to relatively low temperature such as for example 15° above zero or any other higher or lower temperature, if desired, thus providing a means for rapidly congealing the melted wax between the 35 folds of the wrapping material, and which thereby permits the attainment of efficient, long lasting seals.

As there may be some tendency for the ends 40 and bottom of the wrapper to stick to the chilling belts 341 and 342, I have provided at the ends thereof (Figs. 2 and 72) metallic scrapers 405 and 406 which have thin edges, respectively, in substantial engagement with the chilling belts 45 341 and 342. These scrapers 405 and 406 provide an efficient means for breaking the wrapper away from the belts and also for removing any wax that may have accumulated on the chilling belts 341 and 342.

50 By arranging the side chilling belts 342 so that they engage the wrapped article ahead of the lower chilling belts 341 and by having the upper sides of the belts 341 slightly above the plane of the bottom heater plate 290, it will be observed 55 that a slightly curved surface will be presented to the advancing articles which will insure that the overlapping bottom folds will be engaged by the bottom chilling belt 341 and properly chilled. This is particularly advantageous in the case 60 where the bottom of the article, such as bread, is dished, as the overlapping bottom portions of the wrapper will be fully engaged by the bottom belts as they are moved onto the same. Also, as the wrapped article is first engaged by the side 65 belts the side edges of the article, in the case of wrapped bread, will be slightly compressed as the article is carried onto the bottom chilling belts, thus insuring a substantial contact of the bottom of the wrapped article with the bottom 70 chilling belt 341. Reference is made to my pending application, Serial No. 24,515, filed June 1, 1935, the subject matter of which is related to the wrapping material cooling means just described.

75 A suitable limit switch 427 is preferably ar-

ranged in the control circuit of the refrigerating unit which switch is actuated by the clutch of the actuating rod 22.

I have also shown in Figs. 1 and 2, 82 and 83, an attachment for trimming the ends of the 5 wrapping material, in the event the wrapping material is too wide for the article being wrapped. As shown in Figs. 82 and 83, this device comprises a pair of arms 408 hinged to the rear side of the carriage 401 and which carry a rod 409 and an 10 adjustable rod 410. Mounted on the rod 409 are a pair of adjustable brackets 411 each of which carries a knife 412. The wrapping material, as shown in Fig. 82, may pass over the rod 409 and then over rod 410, so that the edges of 15 the knives will lie below the plane of the rods 409 and 410 and thus trim off the edge of the wrapping material 413, the trimmed edge 413 passing downwardly between the rods 409 and 410. The trimming device, when not in use, may 20 be swung out of the way.

In order to observe the action of the wrapping machine, one or more lights 414 (Fig. 2) may be arranged at convenient locations within the 25 machine.

Also, in this connection, I have shown a means for indicating when the supply of wrapping material is nearly exhausted. This comprises a switch means in the circuit of the lights 414 for 30 flashing the lights on and off. This means, as more clearly shown in Fig. 84, includes an arm 415 pivoted to one of the roll supporting arms 39 and having an eccentrically arranged roller 416 thereon which is disposed to engage with the roll of wrapping material, the arms 415 and 39 35 being provided with contacts 417.

When the roll of wrapping material approximates a small diameter, the eccentric roller 416 pivots the arm 415 making and breaking the circuit between switch contacts 417 to cause the 40 lights 414 to flash on and off, thus indicating to the operator of the machine that the supply of wrapping material is about exhausted.

In order to more fully explain the operation of the machine, I will now describe the progress of 45 an article through the machine, using as an example a loaf of sliced bread, and in doing this I shall assume that the machine is open, i. e., a condition in which no wrapped or unwrapped 50 articles are in the machine, and no unwrapped articles are in position to be fed to the elevator table 164.

The drive motor 24 and the motor which drives the refrigerating unit are first started in operation, and also the current supply for the heater 55 plates 290 and 324 is turned on. The clutch operating member 23 is then actuated, which places the drive pulley 7 and the main shaft 4 in driving relation. Although the drive shaft 4 is rotating to drive the infeed conveyor and the cooler 60 belts through the chain belt 161 and the carriage 109 and side grippers 181 and 182 through chain belt 195, the feed rolls 43 and 44, carrier chains 111, cutter 46 and the elevator table 164 do not operate inasmuch as the clutch dog 128 is normally held out of engagement with the clutch arm 130 (Fig. 13) by the follower 133. The trip lever 147 is then manually actuated, which moves the follower 133 out of the path of the lever 127, allowing the dog 128 and arm 130 to engage and 70 thereby drive the shaft 125 in order to operate the carrier chains 111, the feed rolls and the elevator table.

The leading end of the wrapping material is then introduced between the rotating feed rolls 75

43. The cutter 46 also severs the wrapping material, which severed portion is manually removed because in starting the machine it will not be of sufficient length. The trip lever 147 is then 5 again actuated, which then causes the feed rolls 43 and 44 to advance the wrapping material, as indicated in Fig. 56, between the carrier chains 111 where the first and upwardly moving flight 113 engages the underside of the wrapping material and carries the same in an upward direction, and then in a forward direction to drape it over the support 114 (Fig. 56a). The clutch elements 128 and 130 are then disengaged through engagement of cam follower 152 with the cam 10 surface 153, which stops the carrier at approximately the position indicated in Fig. 56a, the elevator table 164 being at this time at its lower article-receiving position (Fig. 5).

Articles to be wrapped are then fed to the in-feed conveyor manually or automatically from a slicing machine. As the first article is being discharged from the infeed conveyor by one of the flights 160h, it engages the trip lever 147 which again places the shaft 125 in driving relation 20 with the main shaft 4. The carrier chains 111 and feed rolls 43 and 44 then start to operate so that the wrapping material is advanced over the wrapping station. The first flight 113 then carries the wrapping material forwardly and at 25 a predetermined time the carriage 209 starts to move forwardly allowing the gripper bar 273 to swing rearwardly into the path of the flight 113 so that as the first flight advances beyond the leading end of the wrapping material the wrapping material is yieldably gripped between the bar 273 and second flight 113, as indicated in 30 Fig. 35, the bar 273 moving forwardly with the flight 113 to place the wrapping material being advanced by the feed rolls under a slight tension. During this movement of the carrier, the wrapping material has been severed by the cutter blade 46 and the elevator table 164 has started to move the sliced article which has been disposed thereon upwardly. During the upward 35 movement of the elevator table 164 the slice alignment bar 370 swings downwardly to engage the sliced article and align the article and then moves back to its normal position out of the path of the upwardly moving elevator table.

50 Just prior to the time the article during its upward travel engages the wrapping material, which has been carried to the position indicated in Fig. 58, the bar 273 has released the wrapping material through the engagement of cam surface 55 275 thereof with the second flight 113. Immediately after this release of the leading end of the wrapping material the trailing end, which has been severed by the cutter blade 46, is discharged from the forward feed rolls 44. During this period, the side grippers 181 and 182 have moved substantially into their gripping position so that upon further upward movement of the elevator table 164 the article engages the under side of the wrapping material and carries it upwardly 60 between the side grippers 181 and 182, the bar 377 having been raised by the elevator table to confine the wrapping material closely against the forward side of the article, as indicated in Fig. 37. During this upward movement the longitudinal 65 ribs of the side grippers 181 and 182 act to smooth out the wrapping material.

The end grippers 184 then swing downwardly and inwardly toward each other to form the top end folds 208 (Fig. 59), the carriage 209 having 70 moved forwardly to bring the forward bottom

fold and roll 213 relatively close to the elevator table. After the side and end grippers have firmly engaged the article with the wrapping material therebetween, the elevator table starts its downward movement, allowing the bar 378 5 to assume its normal position adjacent the forward depending portion of wrapping material. The carriage 209 moves forwardly to fold the rearward depending end of the wrapping material upwardly against the bottom of the article 10 (Fig. 36), during which time the rollers 213 have rotated to smooth out the bottom fold and also during which time the side plates 216 have moved forwardly and progressively formed the rear end folds 206 and fold over the lower portion and 15 crease this lower portion along the bottom edge of the loaf. As the side plates 216 have folded in the rear end folds 206 the end grippers 184 move upwardly out of contacting relation with the top end folds 208. As the carriage 209 approaches the end of its forward movement the forward depending portion of wrapping material is yieldably gripped between the bar 273 and the forward end smoothing roll 213, and as the end 20 of this stroke or movement is reached the side 25 plates 216 move forwardly beyond the front folding roll 213 to overlap with the rear ends of the heater plates 324. The side grippers 181 and 182 then move forwardly to move the article onto the bottom heater plate 290, thus forming the 30 front bottom lap and withdrawing the depending portion of wrapping material from between the roll 213 and bar 378, during which time the rolls 213 have been rotated to further smooth out the wrapping material forming the rear bottom fold.

As the article is moved onto the bottom heater plate 290 the front end folds 292 are formed and folded over the rear end folds 206 after which the carriage 209 and side plates 216 start their 40 retracting movement and the bottom projecting portions of wrapping material have progressed into the slides 333 of the heater side plates 324. During this transfer of the article and the heating device the elevator table has reached its lower 45 position and another sheet of wrapping material has been raised and assumed the position indicated in Fig. 56a.

As the following articles are wrapped and moved to the heater, they move the preceding 50 article forwardly, completing the formation of the bottom end folds 293 which are creased by the creaser plates 337 adjacent the bottom edge of the article. As the wrapped article passes through the heater, the overlapping portions of 55 the wrapper are heated to thus melt the wax in the case of wax paper and practically fuse such portions in the case of regenerated cellulose.

It is not necessary to use the cooling device previously described in the case of the use of 60 regenerated cellulose as a wrapping material. In the case of wax paper, however, the cooler is employed and the wrapped article, as it leaves the heater plates 290 and 324, is first gripped by the side chilling belts 342 and carried onto 65 the bottom chilling belt 341, which, by reason of the prior engagement of the article by the belts 341, allows the article to be engaged by the bottom belts with substantial pressure.

Inasmuch as the refrigerating medium may be 70 at any temperature, such as 15° above zero or lower, the belts 341 and 342 cause the melted wax between the overlapping portions of the wrapper to be quickly chilled, thus providing a very efficient, long lasting seal.

The wrapper provided by the machine has a very neat appearance because of the formation of relatively square corners, which are provided by the creasing of the wrapping material in the manner previously described.

5 The wrapping material employed may be of regenerated cellulose, waxed or unwaxed paper, or any combination thereof, and may be fed from a single roll such as roll 38, shown in Fig. 1, or 10 when two thicknesses of wrapping material are employed, one thickness may be fed from the roll 367. Also, a thin band of material containing, for example, advertising matter, may be supplied from the roll 369 over the material fed from 15 the roll 367, or, if desired, this material may be fed between the two thicknesses of wrapping material being fed from the rolls 38 and 367.

It will be noted that I have incorporated many new and improved features in the wrapping machine described, all of which materially assist in 20 the wrapping of articles and sliced articles in particular, and in the production of a superior wrapper.

Although a single embodiment of the invention 25 has been herein shown and described it will be understood that numerous details of the construction shown may be altered or omitted without departing from the spirit of this invention as defined in the following claims.

30 What I claim is:

1. In a wrapping machine, wrapping mechanism, an article elevator for elevating an article to a position to be wrapped by said mechanism, means for actuating said elevator, a drive 35 for said means, normally disengaged clutch elements associated with said means and drive, a conveyor for successively discharging articles onto said elevator after each actuation thereof, and a trip member operatively connected with 40 one of said clutch elements for causing upon actuation thereof driving engagement between said clutch elements, said trip member being disposed to be engaged and actuated only by an article being discharged by said conveyor, where- 45 by driving engagement of said clutch elements and actuation of said elevator is effected only when an article is being discharged by said conveyor.

2. In a wrapping machine, wrapping mechanism, an article elevator for elevating an article to a position to be wrapped by said mechanism, means for actuating said elevator, a drive for 50 said means, normally disengaged clutch elements associated with said means and drive, a conveyor for successively discharging articles onto said elevator after each actuation thereof, a trip member operatively connected with one of said clutch elements for causing upon actuation thereof driving engagement between said clutch elements, said trip member being discharged by said conveyor, whereby driving engagement of 55 said clutch elements and actuation of said elevator is effected only when an article is being discharged by said conveyor, and means for dis- 60 engaging said clutch elements after said elevator has completed its elevating movement and re- turned to its article receiving position.

3. In a wrapping machine, wrapping mechanism, means for advancing wrapping material to 70 said mechanism, an elevator for moving an article to a wrapping position, a conveyor for successively discharging articles onto said elevator, means for driving said advancing means, a drive for said driving means, normally disengaged clutch elements associated with said drive

and driving means, and a trip member operatively connected with one of said clutch elements for effecting upon actuation thereof driving connection between said clutch elements, said trip member being disposed to be engaged 5 and actuated only by an article being discharged by said conveyor, whereby driving engagement between said clutch elements and advancing movement of said advancing means is effected only when an article is being discharged by said 10 conveyor.

4. In a wrapping machine, wrapping mechanism, means for advancing wrapping material to said mechanism, an elevator for moving an article to a wrapping position, a conveyor for 15 successively discharging articles onto said elevator, means for driving said advancing means, a common means for driving said elevator and advancing means, a drive for said advancing means, normally disengaged clutch elements 20 carried by said common means and drive, and a trip member operatively connected with one of said clutch elements for effecting upon actuation thereof driving connection between said elements, said trip member being disposed to be 25 engaged and actuated only by an article being discharged by said conveyor, whereby driving engagement between said clutch elements and operation of said elevator and advancing means 30 is effected only when an article is being discharged by said conveyor.

5. In a wrapping machine, wrapping mechanism, means for advancing wrapping material to said mechanism, an elevator for moving an article to a wrapping position, a conveyor for 35 successively discharging articles onto said elevator, means for driving said advancing means, a common means for driving said elevator and advancing means, a drive for said advancing means, normally disengaged clutch elements carried by said common means and drive, a trip member operatively connected with one of said clutch elements for effecting upon actuation thereof driving connection between said elements, said trip member being disposed to be engaged 40 and actuated only by an article being discharged by said conveyor, whereby driving engagement between said clutch elements and operation of said elevator and advancing means is effected only when an article is being discharged by said conveyor, and means for automatically disengaging 45 said clutch elements after a predetermined operation of said common driving means.

6. In a wrapping machine, means for supporting an article in wrapping position below a sheet 55 of wrapping material, a pair of spaced oscillatory arms, end grippers pivoted in said arms to swing toward and away from each other, said grippers normally being disposed above the sheet of wrapping material and normally being swung outwardly away from each other, means for swinging said arms downwardly to move side portions of the sheet downwardly adjacent the ends of the article, and means for swinging said grippers inwardly toward each other to fold said portions 60 of wrapping material firmly against the ends of the article to form the top end folds, said first mentioned swinging means being arranged to return said grippers through the path of swinging 65 portions to their normal position.

7. In a wrapping machine, means for holding the article to be wrapped with the ends of the wrapping material projecting beyond the bottom of the article, mechanism for folding one of said ends upwardly and against the bottom of the 75

- article, said mechanism comprising a reciprocal carriage, means for moving said carriage, and means on said carriage to engage the said projecting end and fold it upwardly against the bottom of the article, said last mentioned means being movable during the folding operation in the direction of folding movement to smooth out the wrapping material during such operation, said last mentioned means being movable independently of the movement of said carriage.
8. In a wrapping machine, means for holding the article to be wrapped with the ends of the wrapping material projecting beyond the bottom of the article, mechanism for folding one of said ends upwardly and against the bottom of the article, said mechanism comprising a reciprocal carriage, means for moving said carriage, and means on said carriage to engage the said projecting end and fold it upwardly against the bottom of the article, said last mentioned means being movable during the folding operation in the direction of folding movement to smooth out the wrapping material during such operation, said last mentioned means including an endless belt carried by said carriage.
9. In a wrapping machine, means for holding the article to be wrapped with the ends of the wrapping material projecting beyond the bottom of the article, mechanism for folding one of said ends upwardly and against the bottom of the article, said mechanism comprising a reciprocal carriage, means for moving said carriage, and means on said carriage to engage the said projecting end and fold it upwardly against the bottom of the article, said last mentioned means being movable during the folding operation in the direction of folding movement to smooth out the wrapping material during such operation, said last mentioned means comprising a roller of relatively small diameter carried at the front end of said carriage, a roller rearwardly of said first roller, an endless belt carried by said rollers, and means for rotating one of said rollers.
10. In a wrapping machine, a source of wrapping material, a wrapping station, means for supporting an article at said station, means for advancing wrapping material to said station above the article including feed rolls, a carriage for supporting said rolls, a cutter carried by said carriage for severing the wrapping material, means for folding the severed wrapping material about the article with the ends thereof overlapped at the bottom of the article, and means for moving the carriage to predetermine the position of the overlapping of said ends.
11. In a wrapping machine, means for holding the article to be wrapped in a suspended position with an end of the sheet of wrapping material engaging the sides of the article and hanging downwardly beyond the bottom of the article, a device movable beneath the article for folding said end into engagement with the bottom of the article, said device comprising a rotatable roller, and means for bodily moving said roller into engagement with the said projecting end of wrapping material and into an underlying position with respect to the article whereby movement of said roller folds and carries said end upwardly into engagement with the bottom of the article.
12. In a wrapping machine, means for holding the article to be wrapped with an end of the sheet of wrapping material engaging the sides of the article and projecting downwardly beyond the bottom of the article, a device movable beneath the article for folding said end into en-

gagement with the bottom of the article, said device comprising a rotatable roller, and means for bodily moving said roller into engagement with the said projecting end of wrapping material and into an underlying position with respect to the article whereby movement of said roller folds and carries said end upwardly into engagement with the bottom of the article, and means for retracting said roller, said device also including means for rotating said roller both during folding and retracting movement thereof to smooth out said wrapping material.

13. In a wrapping machine, means for holding the article to be wrapped with the ends of the sheet of wrapping material projecting beyond the bottom of the article, a device for folding one of said ends into engagement with the bottom of the article, said device comprising a plurality of rollers, and means for bodily moving said rollers into engagement with the said projecting end of wrapping material and into overlapping position with respect to the article whereby movement of said rollers folds and carries said end into engagement with the bottom of the article.

14. In a wrapping machine, means for holding the article to be wrapped with the ends of the sheet of wrapping material projecting beyond the bottom of the article, a device for folding one of said ends into engagement with the bottom of the article, said device comprising a plurality of rollers, and means for bodily moving said rollers into engagement with the said projecting end of wrapping material and into overlapping position with respect to the article whereby movement of said rollers folds and carries said end into engagement with the bottom of the article, said device also including means for rotating said rollers during the folding movement thereof in the direction of such movement.

15. In a wrapping machine, means for holding the article to be wrapped with the ends of the sheet of wrapping material projecting beyond the bottom of the article, a device for folding one of said ends into engagement with the bottom of the article, said device comprising a plurality of rollers, and means for bodily moving said rollers into engagement with the said projecting end of wrapping material and into overlapping position with respect to the article whereby movement of said rollers folds and carries said end into engagement with the bottom of the article, and means for retracting said rollers.

16. In a wrapping machine, means for holding the article to be wrapped with the ends of the sheet of wrapping material projecting beyond the bottom of the article, a device for folding one of said ends into engagement with the bottom of the article, said device comprising a plurality of rollers, and means for bodily moving said rollers into engagement with the said projecting end of wrapping material and into overlapping position with respect to the article whereby movement of said rollers folds and carries said end into engagement with the bottom of the article, and means for retracting said rollers, said device also including means for rotating said rollers both during folding and retracting movement thereof to smooth out said wrapping material.

17. In a wrapping machine, means for holding the article to be wrapped with the ends of the sheet of wrapping material projecting beyond the bottom of the article, a device for folding one of said ends into engagement with the bottom of the article, said device comprising a movable

carriage, one or more rotatable rollers carried by said carriage to engage with the said projecting end of wrapping material and move the same into engagement with the bottom of the article to be wrapped during movement of said carriage, and means for moving said carriage.

18. In a wrapping machine, means for holding the article to be wrapped with the ends of the sheet of wrapping material projecting beyond the bottom of the article, a device for folding one of said ends into engagement with the bottom of the article, said device comprising a movable carriage, one or more rotatable rollers carried by said carriage to engage with the said projecting end of wrapping material and move the same into engagement with the bottom of the article to be wrapped during movement of said carriage, and means for moving said carriage, said device including a gear on said roller and a rack meshed therewith, whereby to rotate said roller during movement of said carriage and thereby iron out said wrapping material.

19. In a wrapping machine, means for holding the article to be wrapped with the ends of the sheet of wrapping material projecting beyond the bottom of the article, a device for folding one of said ends into engagement with the bottom of the article, said device comprising a movable carriage, one or more rotatable rollers carried by said carriage to engage with the said projecting end of wrapping material and move the same into engagement with the bottom of the article to be wrapped during movement of said carriage, and means for moving said carriage, said device including a gear on said roller and a rack meshed therewith, whereby to rotate said roller during movement of said carriage and thereby iron out said wrapping material, and means to move said rack whereby to rotate said roller independently of the movement of said carriage.

20. In a wrapping machine, means for supporting a sheet of wrapping material in a substantially horizontal position, a movable elevator table, means for depositing an article to be wrapped onto said table, means for moving said table in an upward arcuate path to position the article in engagement with the lower surface of the sheet intermediate the ends thereof, and means to retract said table, and gripping devices for securely engaging and holding the article during retraction of said table, said last mentioned means comprising an arm connected with said table, a pair of spaced swingable crank arms of unequal length pivoted to said arm, and cam means for one of said arms, whereby to provide arcuate movement of said table.

21. In a wrapping machine, means for supporting a sheet of wrapping material in a substantially horizontal position, a movable elevator table, means for depositing an article to be wrapped onto said table, means for moving said table in an upward arcuate path to position the article in engagement with the lower surface of the sheet intermediate the ends thereof, and means to retract said table, and gripping devices for securely engaging and holding the article during retraction of said table, said article depositing means having spaced article guides, and projecting guides pivoted thereto to extend over said table to center the article thereon, said projecting guides being pivoted by the movement of said table.

22. In a wrapping machine for disposing wrapping material about an article, means for heating the overlapped portions provided by the

wrapping of the wrapping material about the article, said means comprising a base plate for supporting the wrapped article, a pair of spaced vertical plates for engaging the ends of the wrapped article and means for heating each of said plates, the article engaging face of each of said plates being composed of a plurality of transversely extending non-yielding ribs integrally formed thereon in direct metallic heat conductive relation with said heating means, at least one face of each rib being inclined substantially from the top thereof to the base of the next rearwardly adjacent rib.

23. In a wrapping machine, a pair of feed rolls for advancing wrapping material, a wrapping station, and means for gripping the leading end of the wrapping material and carrying the same to said wrapping station while said material is being advanced by said rolls, said gripping means being arranged to yieldably hold said material with sufficient friction to keep said material taut but with insufficient friction to advance said material independently of said rolls.

24. In a wrapping machine, a pair of feed rolls for advancing wrapping material, a wrapping station, means for gripping the leading end of the wrapping material and carrying the same to said wrapping station while said material is being advanced by said rolls, said gripping means being arranged to yieldably hold said material with sufficient friction to keep said material taut but with insufficient friction to advance said material independently of said rolls, and means for disengaging said gripping means from said material just prior to the discharge of the trailing end of said material from said feed rolls.

25. In a wrapping machine, a pair of feed rolls for advancing wrapping material, a wrapping station, a bar movable through an endless path for engaging the under side of the material being advanced and carrying the leading end thereof over said wrapping station while the material is being advanced and held by said rolls, and a second bar disposed to yieldably hold said leading end against said first bar and to move with said first bar, whereby to yieldably hold the advanced wrapping material with sufficient friction to keep said material taut but with insufficient friction to advance said material independently of said rolls.

26. In a wrapping machine, a pair of feed rolls for advancing wrapping material, a wrapping station, a bar movable through an endless path for engaging the under side of the material being advanced and carrying the leading end thereof over said wrapping station while the material is being advanced and held by said rolls, a second bar disposed to yieldably hold said leading end against said first bar and to move with said first bar, whereby to yieldably hold the advanced wrapping material with sufficient friction to keep said material taut but with insufficient friction to advance said material independently of said rolls, and means to disengage said second bar from said leading end just prior to the discharge of the trailing end of said wrapping material from said rolls.

27. In a wrapping machine, a means for supporting a sheet of wrapping material in a generally horizontal position, a horizontal bar above the normal position of the sheet and being movable in a generally upward direction, an elevator for moving an article from a lower position to an upper position into engagement with said sheet intermediate the ends thereof whereby to drape

- 5 said sheet about the top and sides of the article, said bar being in the path of movement of said elevator and movable upwardly therewith to position the leading portion of said sheet adjacent 5 to the side of the article and on said elevator, means for holding the article in its elevated position, and means for lowering said elevator after the article is so held, said bar being movable back to its lower normal position upon lowering movement of said 10 elevator, and below the bottom of the article, the leading portion of wrapping material extending below the bottom of the article and in front of said bar.
- 15 28. In a wrapping machine, a means for supporting a sheet of wrapping material in a generally horizontal position, a horizontal bar above the normal position of the sheet and being movable in a generally upward direction, an elevator for moving an article from a lower position to an 20 upper position into engagement with said sheet intermediate the ends thereof whereby to drape said sheet about the top and sides of the article, said bar being in the path of movement of said elevator and movable upwardly therewith to position 25 the leading portion of said sheet adjacent the side of the article and on said elevator, means for holding the article in its elevated position, and means for lowering said elevator after the article is so held, said bar being movable back to its lower normal position upon lowering movement of said 30 elevator, and below the bottom of the article, the leading portion of wrapping material extending below the bottom of the article and in front of said bar, said machine including 35 a horizontally reciprocable member movable toward said bar for forming a rear bottom fold and movable into engagement with said bar to yieldably grip the downwardly projecting leading portion of wrapping material therebetween, and 40 means for moving the article forwardly over said bar to draw the said leading portion from between said reciprocable member and bar.
- 45 29. In a wrapping machine, means for suspending an article with a sheet of wrapping material extending over the top and sides thereof and with the end portions of the material projecting downwardly below the bottom of the article, a horizontal bar normally disposed near but below the bottom of the article and adjacent one of said 50 end portions, and reciprocable means movable to fold the other of said end portions into engagement with the bottom of the article and movable toward said bar to yieldably grip the other end portion between said bar and last mentioned 55 means, said suspending means being movable over said bar to withdraw the gripped end portion of material from between said bar and reciprocable means.
- 60 30. In a wrapping machine, means for folding a projecting side portion of wrapping material against an end of an article, comprising a reciprocable vertical plate having its forward edge inclined downwardly and rearwardly whereby to progressively fold said portion from its upper to its lower edge, said plate including a laterally projecting flange for rolling a portion of the projecting wrapping material over the horizontally projecting portion of the wrapping material.
- 65 31. In a wrapping machine, means for folding a projecting side portion of wrapping material against an end of an article, comprising a reciprocable vertical plate having its forward edge inclined downwardly and rearwardly whereby to progressively fold said portion from its upper to 70 its lower edge, said plate including a laterally

projecting flange intermediate its top and bottom portions and projecting forwardly beyond the adjacent forward edge of the plate for lapsing a lower portion of the projecting side portion of wrapping material over a bottom portion of the wrapping material during the said progressive folding of the side portion. 5

32. In a wrapping machine, means for folding a projecting side portion of wrapping material against an end of an article, comprising a reciprocable vertical plate having its forward edge inclined downwardly and rearwardly whereby to progressively fold said portion from its upper to its lower edge, said plate including a laterally projecting flange intermediate its top and bottom portions and projecting forwardly beyond the adjacent forward edge of the plate for lapsing a lower portion of the projecting side portion of wrapping material over a bottom portion of the wrapping material during the said progressive folding of the side portion, the bottom edge of said plate being arranged to crease the overlapped portions along and closely adjacent to the bottom edge of the article. 10 15

33. In a wrapping machine, means for folding a projecting side portion of wrapping material against an end of an article, comprising a reciprocable vertical plate having its forward edge inclined downwardly and rearwardly whereby to progressively fold said portion from its upper to its lower edge, said plate including a laterally projecting flange intermediate its top and bottom portions and projecting forwardly beyond the adjacent forward edge of the plate for lapsing a lower portion of the projecting side portion of wrapping material over a bottom portion of the wrapping material during the said progressive folding of the side portion, the bottom edge of said plate being arranged to crease the overlapped portions along and closely adjacent to the bottom edge of the article. 20 25

34. In a wrapping machine, a base plate, a pair of spaced side plates adjacent said base plate, 45 each of said side plates having a slot therein opening through the bottom edge thereof, one face of the slot being inclined upwardly from the bottom thereof for folding a bottom projecting portion of wrapping material against an end of a partially wrapped article being passed between said side plates, each of said plates having a spring held creaser plate projecting through the slot thereof and having a corner adjacent said base plate for creasing the projecting portion of wrapping material adjacent the bottom end edge of the article during the folding operation. 50 55

35. In a wrapping machine, a reciprocable carriage, means on said carriage for forming a bottom fold, a pair of side members for forming end folds, said members being supported by and reciprocably mounted on said carriage, means for reciprocating said carriage and means for reciprocating said side members in relation to said carriage. 60 65

36. In a wrapping machine, a reciprocable carriage, means on said carriage for forming a bottom fold, a pair of side members for forming end folds, said members being supported by and reciprocably mounted on said carriage, means for reciprocating said carriage and means for reciprocating said side members in relation to said carriage, said side members being movable beyond said first means. 70

37. In a wrapping machine, a reciprocable car- 75

riage having a forward and a rearward movement, means on said carriage for folding a wrapping portion against an article during the forward movement, a carriage drive and a resilient connection between said drive and carriage operative during said forward movement to resiliently actuate said carriage.

38. In a wrapping machine, a reciprocable carriage having a forward and a rearward movement, means on said carriage for folding a wrapping portion against an article during the forward movement, a pivoted drive arm connected with said carriage for reciprocating said carriage, a rotatable cam, a cam follower engaged with said cam, and a resilient connection between said follower and arm, whereby to resiliently actuate said arm.

39. In a wrapping machine, a wrapper sealing device including a bottom member and spaced side members, a reciprocable carriage having means thereon for forming a bottom fold of wrapping material against an article, said carriage being movable toward said sealing device, means for limiting said forward movement to a position adjacent said bottom member, spaced side tuckers carried by said carriage and being reciprocable beyond the limited forward position of said carriage to overlap said side members, and means for moving the wrapped article from between said side tuckers to a position between said side members.

40. In a wrapping machine having a wrapping station, an elevator table movable from a lower position to an upper position to transfer an article to the wrapping station, means for depositing an article to be wrapped onto said table while said table is in its lower position, spaced guides associated with said depositing means, spaced guides on said table, guides pivoted to said first mentioned guides to extend over and rest on said table in alignment with said table guides and being pivoted by upward movement of said table, means to move said table upwardly, and means at said wrapping station to grip the article elevated by said table.

41. In a wrapping machine means for folding a projecting side portion of wrapping material against an end of an article to be wrapped, comprising a reciprocable plate having a laterally projecting flange portion intermediate its side edges and projecting beyond the leading end edge of said plate for lapping a part of said side portion of wrapping material over another portion of the wrapping material during the folding of said side portion against the end of the article.

42. In a wrapping machine, a base plate, a pair of spaced side plates adjacent said base plate, each of said side plates having a slot therein opening through the bottom edge thereof, one face of the slot being inclined upwardly from the bottom thereof for folding a bottom projecting portion of wrapping material against an end of a partially wrapped article being passed between said side plates, each of said side plates having a creaser plate extending through the slot thereof toward said base plate and having an edge adjacent said plate for creasing the projecting portion of wrapping material adjacent the bottom end edge of the article during the folding operation.

43. In a wrapping machine, a base plate, a pair of spaced side plates adjacent said base plate, each of said side plates having a slot therein opening through the bottom edge thereof, one face of the slot being inclined upwardly from the

bottom thereof for folding a bottom projecting portion of wrapping material against an end of a partially wrapped article being passed between said side plates, each of said side plates having an inner wrapper engaging face and a creaser member, said creaser member having an edge adjacent to the lower edge of the said wrapper engaging face and adjacent to said base plate and the bottom of the slot in the said side plate for creasing the projecting portion of wrapping material adjacent the bottom end edge of the article during the folding operation.

44. In a wrapping machine, a base plate, a pair of spaced side plates adjacent said base plate, each of said side plates having a slot therein opening through the bottom edge thereof, one face of the slot being inclined upwardly from the bottom thereof for folding a bottom projecting portion of wrapping material against an end of a partially wrapped article being passed between said side plates, each of said side plates having an inner wrapper engaging face and a creaser member, said creaser member having an edge adjacent to the lower edge of the said wrapper engaging face and adjacent to said base plate and the bottom of the slot in the said side plate for creasing the projecting portion of wrapping material adjacent the bottom end edge of the article during the folding operation, said creaser member being inclined relative to the said wrapper engaging face and extending through the said slot.

45. In a wrapping machine for disposing wrapping material about an article, means for heating the overlapping portions provided by the wrapping of the wrapping material about the article, comprising a bottom plate for supporting the article, a pair of spaced supports disposed above said bottom plate, and a vertical side heater plate associated with each of said supports, said side plates and supports having cooperating means for quickly attaching said side plates to and removing said side plates from said supports.

46. In a wrapping machine for disposing wrapping material about an article, means for heating the overlapping portions provided by the wrapping of the wrapping material about the article, comprising a bottom plate for supporting the article, a pair of spaced supports disposed above said bottom plate, and a vertical side heater plate associated with each of said supports, said side plates and supports having cooperating means for quickly attaching said side plates to and removing said side plates from said supports, said last mentioned means comprising pins and pivoted arms having pin receiving slots therein.

47. In a wrapping machine for sliced bread loaves, means for supporting a sliced loaf in wrapping position below a sheet of wrapping material and intermediate the side edges thereof, an oscillatory shaft, a pair of spaced arms carried by said shaft for oscillation therewith, end gripper supports mounted on said arms for oscillation with respect to the axes of said arms, end grippers secured to said supports for oscillation therewith, said end grippers normally being widely divergent downwardly from the plane of the axes of said supports and arms, and normally being above the wrapping material, means for oscillating said shaft to swing said end grippers downwardly to move the side edges of the sheet of wrapping material downwardly adjacent the ends of the loaf, and means for oscillating said supports to move said grippers inwardly toward

- each other to straighten the slices of the loaf being wrapped and to fold said side edges of wrapping material firmly against the ends of the loaf to form the top end folds.
- 5 48. In a wrapping machine for sliced bread loaves, means for positioning a sliced bread loaf below and in engagement with a sheet of wrapping material, with the ends of the wrapping sheet projecting down the sides and beyond the 10 loaf, and the sides of the sheet projecting beyond the ends of the loaf, an oscillatory shaft, a pair of end grippers mounted for movement by said shaft, said end grippers normally being widely divergent and normally being above the wrapping 15 material, means for oscillating said shaft to swing said end grippers downwardly, and means to simultaneously move said end grippers inwardly to engage the side edges of the sheet of wrapping material projecting beyond the ends of the loaf 20 and move the wrapping material downwardly adjacent the ends of the loaf to straighten the slices of the loaf being wrapped and to fold said side edges of wrapping material firmly against the edges of the loaf to form the top end folds.
- 25 49. In a wrapping machine, a wrapper sealing device comprising a base plate for supporting a wrapped article, a pair of spaced, vertical plates for engaging the ends of the wrapped article, and a heating means for each of said plates, the 30 wrapped article engaging surface of each of said plates having non-yielding ridges integrally formed thereon in direct metallic heat conductive relation with said heating means, said ridges extending transversely of the direction of movement of the wrapped article and having substantially smooth wrapper-contacting portions, whereby the ridges have a stroking action on the wrapper, and said ridges having relatively short, 35 steeply sloping faces on the side of the crest of the ridges positioned in the direction of travel of the wrapped articles and relatively long, gradually sloping faces on the side of the crest of the ridges from which the wrapped articles approach.
- 40 50. In a wrapping machine, a wrapper sealing device comprising a base plate for supporting a wrapped article, a pair of spaced, vertical plates for engaging the ends of the wrapped article, and a heating means for each of said plates, the wrapped article engaging surface of each of said plates having non-yielding ridges integrally formed thereon in direct metallic heat conductive relation with said heating means, said ridges extending transversely of the direction of movement of the wrapped article and having substantially smooth wrapper-contacting portions, and said ridges spaced at relatively wide intervals so that irregular raised portions on the wrapped article may be positioned between successive ridges and the said successive ridges 55 uniformly engage the overlapped wrapper portions in the hollows of the wrapped article adjacent the raised portions.
- 55 51. In a wrapping machine, a wrapper sealing device comprising a base plate for supporting a wrapped article, a pair of spaced vertical plates for engaging the ends of the wrapped article and a heating means for each of said plates, the wrapped article engaging surface of each of said plates having non-yielding ridges integrally formed thereon in direct metallic heat conductive relation with said heating means, said ridges extending transversely of the direction of movement of the wrapped article and having substantially smooth wrapper contacting portions, said

ridges having relatively short, steeply sloping faces on the side of the crest of the ridges in the direction of travel of the wrapped article and relatively long, gradually sloping faces on the side of the crest of the ridges from which the wrapped article approaches, and said ridges spaced at relatively wide intervals so that irregular raised portions on the wrapped article may be positioned between successive ridges and said successive ridges engage overlapped wrapper portions in hollows of the wrapped article adjacent the raised portions.

5 52. In a wrapping machine a pair of feed rolls for advancing the free end of a continuous web of wrapping material, a wrapping station, means 15 for gripping the leading end of the wrapping material and carrying the same to said wrapping station while said material is being advanced by said rolls, said gripping means being arranged to yieldably hold said material with sufficient friction to keep said material taut but with insufficient friction to advance said material independently of said rolls, means for severing the advanced wrapping material from the web and means for disengaging said gripping means from 25 said material just after the severing of the material by the severing means.

20 53. In a wrapping machine a pair of feed rolls for advancing the free end of a continuous web of wrapping material, a wrapping station, a bar 30 movable through a predetermined path to engage the underside of the material being advanced and carry the leading end thereof across the wrapping station while the material is being advanced and held by the rolls, and a second bar disposed 35 to yieldably hold said leading end against said first bar and move with said first bar, whereby to yieldably hold the advanced wrapping material with sufficient friction to keep said material taut, but with insufficient friction to advance said material independently of said rolls.

35 54. In a wrapping machine means for folding a projecting side portion of wrapping material against an end of an article to be wrapped, comprising a plate having a laterally projecting 45 flange portion intermediate and spaced from both side edges and projecting beyond the leading end edge of said plate for lapping a part of said side portion of wrapping material over another portion of the wrapping material during the folding 50 of said side portion against an end of an article, and means for causing a relative movement of the plate across the end of an article.

40 55. In a wrapping machine a base plate, a pair of spaced side plates adjacent to said base plate, 55 each of said side plates having a slot therein opening through the bottom edge thereof, one face of the slot being inclined upwardly from the bottom thereof for folding a bottom projecting portion of wrapping material against an end of a 60 partially wrapped article being passed between said side plates, each of the side plates having an inner wrapper engaging face, each of the side plates having a creaser member pivoted thereon above the slot and normally extending across the 65 slot and the said creaser member normally having an edge adjacent to the lower edge of the said wrapper engaging face and adjacent to said base plate near the bottom of the slot in the said side plate for creasing a projecting portion of 7 wrapping material adjacent the bottom end edge of an article during a folding operation.
